PRINTING MACHINE

Carl J. Hueber, Euclid, Ohio, assignor to Addressograph-Multigraph Corporation, Wilmington, Del., a corporation of Delaware

Application June 22, 1942, Serial No. 447,961

34 Claims. (Cl. 101—47)

This invention relates to printing machines through which a series of printing devices may be passed seriatim to a printing position whereat impressions may be made from the devices, and more particularly this invention has to do with a mechanism to be used in such printing machines to enable a plurality of impressions to be made in succession at different locations upon a sheet advanced through the machine.

In the use of printing machines of the aforesaid character it is customary to employ printing devices having a series of lines of printing characters disposed upon the printing device with the lines one above the other in what may be termed a single column, and the printing impressions are usually made from the printing characters on the printing device so that these printing characters are printed upon the sheet or form in precisely the same arrangement. Such printing machines are so constructed that the printing devices are withdrawn one by one from a supply magazine and are advanced in a step-by-step manner to a printing position in the machine. At such printing position, the sheet or form, or a manifold arrangement of a plurality of paper sheets and carbon paper, is disposed in the desired relationship to the printing device and while the printing device remains stationary at printing position suitable impression means are operative to make the desired printing impressions from the type characters of the printing device onto the sheet. Various arrangements have heretofore been provided whereby selected portions of the type characters carried on a printing device might be printed to the exclusion of other type characters, and hence the printing devices in many instances may embody considerable information pertaining to a particular subject or person, and selected parts of this information may be printed as desired. The information carried by the printing devices is advantageously arranged so that it is adaptable for the most common uses to which such printing devices may be put. Thus, for example, a printing device may embody the name, the street address and the city and state of residence of a person to which a particular device relates, and in addition there may be a fourth line of type characters constituting a salutation whereby the name and address data and the salutation may be printed upon a letter which is to be sent to the particular person to which the printing device pertains. Further or different data may of course be embodied in such a printing device either at the ends of the lines in which the aforesaid

mentioned data are embodied, or in additional lines of type characters or in special applications, numerical and other data may be included on the device.

5 In other instances the printing devices employed with such printing machines may be adapted for use in a variety of accounting operations to produce related records or documents, and many of such documents may be advantageously produced by what are called listing operations on a printing machine of the aforesaid character. Where the printing devices are intended for use in payroll work, each printing device may carry lines of printing characters which 10 set forth the name of an employee, related identifying data such as his address and social security number, his normal rate of pay upon an hourly, weekly, or other basis, the various deductions to be made from the employee's pay for 15 each payroll period, and, in the event that the employee works upon a fixed salary basis, his gross salary, and his net salary after the stated deductions may also be included in words, or figures, or both. Such printing devices may also 20 be used for accounting operations in banks, trust companies, insurance companies and the like, in which case the data carried by the printing devices will, of course, vary in accordance with the particular uses for which they are intended. 25 20 Where printing devices bearing data of the various classes as aforesaid have been utilized in listing operations such as the preparation of payroll sheets, or sheets of dividend checks, payroll checks or the like, it has been customary to clamp 30 the sheet, or a manifold arrangement of sheets, in the shiftable paper holder of the listing apparatus, which is commonly referred to as a lister, of which the single column lister shown in the 35 patent to Curtis, No. 2,186,010, patented January 9, 1940, or the multiple column lister shown in my copending application, Serial No. 410,097 filed September 8, 1941, are exemplary, so that the paper holder and the sheet or sheets clamped thereon are advanced in a step by step manner 40 45 from an initial or loading position to a succession of other positions the last of which constitutes the terminal position in which the final printing impression is made upon the sheet or sheets. The terminal position of the paper holder is usually attained at an extreme end of its range of movement, and hence, in order to prevent repetitious or other undesired printing at the last position on the sheet where the impression is to be made, the printing operation of 50 55 the printing machine must invariably be termi-

nated after the final impression has been made upon a sheet, or a manifold arrangement of sheets, thus located in the terminal position, and to enable this to be accomplished in a simple and expeditious manner is an important object of this invention.

After completion of the desired series of printing or listing operations on a sheet or sheets as aforesaid, it has heretofore been necessary for the operator to manually withdraw or return the paper holder and the completed sheet to their initial positions for removal and replacement of the sheet and it is a further important object of this invention to effect return of the paper holder of a lister, and the sheet or sheets carried thereby, to the initial or loading position by power actuated means, and an object related to the foregoing is to enable such return movement to be effected automatically.

When the paper holder of a lister is returned to its initial or loading position, the paper clamps thereof must be released so that the completed sheet may be removed therefrom, and to further simplify the use of such a lister it is an object of this invention to release the paper clamps automatically when the desired printing operations have been completed, and more specifically, to accomplish such automatic release as an incident to the return of the paper holder to its loading position.

In the use of a lister with a printing machine it may be desirable in many instances to skip, or in other words, to avoid printing in one or more spaces of the form, and to enable this to be readily and easily accomplished is a further object of the invention. Other objects related to the foregoing are to enable spacing or advancing movements to be imparted manually to the paper holder, to enable power actuated return movements of the paper holder to be initiated readily and easily from any one of the operative positions of the lister, and to enable the means for attaining such manually manual spacing or manually initiated return movements to be incorporated in a simple and easily connected structure.

A listing mechanism of the kind to which the present invention pertains must, as a practical matter, be readily adaptable for use with forms embodying different line spacing dimensions, and in prior listers such as that shown in the aforesaid Curtis patent, and such as that shown in my aforesaid copending application, this has been advantageously accomplished through the use of replaceable elements which act as a portion of the advancing means for the paper holder and which may be formed to provide for the desired line spacing movements. A further object of this invention is to enable such replaceable elements of a lister to control the initiation of the return movement of the paper holder, and another object is to enable such a replaceable element not only to control the automatic return of the paper holder but also to interrupt and stop the operation of the printing mechanism upon completion of the last printing impression on a sheet.

The replaceable connecting elements shown in the aforesaid Curtis patent and in my aforesaid copending application are relatively flexible in character and function to actuate the paper holder in but one direction, and a further object of this invention is to enable such flexible connecting elements to impart both advancing and return movements to the paper holder of a lister;

and a further object related to the foregoing is to so form such a flexible element that it may be readily and easily entered into an operative association with a return actuating means, thereby to facilitate the replacement of such connecting elements.

Such a connecting element of the advancing means for the paper holder which is thus replaced in a lister mechanism to obtain different line spacing movement is, under the present invention, utilized as a connecting means through which the return actuating movement is transmitted from actuating means on the lister frame to the paper holder, and through which the extent of such return movement is accurately limited, and under such circumstances the manner of association between the connecting element and the return actuating means must not only be such as to enable such controlled return movement of the paper holder to be attained, but also must be of such a character as to facilitate replacement of the connecting element, and to enable this to be accomplished is a further object of the invention.

A further object of this invention is to constantly bias the paper holder of a lister in a return direction toward its initial or loading position and to afford means for controlling the biasing means in such a manner that either automatic or manually controlled return movement of the paper holder may be effected.

Other and further objects of the present invention will be apparent from the following description and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claims.

General description

In the form chosen for disclosure herein, the invention is embodied in a printing apparatus comprising a printing machine 40 having a listing device 41 operatively associated therewith in such a manner that a sheet or form F, or a manifold arrangement of a plurality of sheets and carbon paper, mounted on a paper holder 42 of the lister 41 may be shifted to the printing position of the machine in a step by step manner in timed relation to the operation of the printing machine, thereby to enable successive printing impressions to be spaced from each other on the form F in a direction from top to bottom of the form. The listing device 41 is unitary in character and is so related to the printing machine 40 that the listing device 41 may be quickly and easily placed in the desired operative relation upon the printing machine 40, or may be quickly and easily removed from such operative association when the desired listing operations have been completed. The listing device 41 of the present invention is such that the operator may perform the listing operations with unusual facility, and in attaining this result the listing device 41 of the present invention includes means for automatically returning the paper holder of the lister to its forward or loading position when the listing operations upon a particular sheet have been completed. The lister of this invention also provides for manual advancing or spacing of the form, and for manual rather than automatic initiation of the return movement of the paper holder to its loading position. The arrangement of the listing device 41 is such that it may be used upon sheets or forms having different line spacing arrangements, and the ad-

justment of the listing device to condition it for use with forms having a different line spacing may be accomplished readily and easily by the usual operator of the machine. When the listing device of the present invention has been adjusted so as to perform listing operations with a particular form or with a particular spacing of impressions, the listing device may be removed from and then replaced upon the printing machine without disturbing such adjustments.

Insofar as the present invention is concerned, the particular form and arrangement of the printing machine 40 are in most instances immaterial, but for purposes of disclosure the printing machine 40 is illustrated as being of the type wherein a series of individual printing devices D, each bearing printing means thereon, are advanced one by one from a supply means such as an upstanding magazine M to a printing position which is provided in the machine and which is indicated in Fig. 2 by the dotted line position of the printing device D. The magazine M is located upon and supported by a printing machine frame 43 which, in the form shown, is generally desk-like in character so as to provide a table top T upon which a sheet or form F may be supported over the printing position and beneath an impression means such as a platen mechanism P for the performance of printing operations with respect to the form. In the operation of the printing machine 40, the printing devices D are withdrawn one by one from the bottom of the magazine M and are advanced in a step by step manner along a suitable printing device feed path beneath the table top T until each printing device comes to rest at printing position. While the printing device D is at rest at the printing position, the platen mechanism P is operated to produce a printing impression from all or selected portions of the type characters embodied in the printing device. After one or more printing impressions have been made from the printing device, it is further advanced so as to be discharged into a collecting means such as a drawer K. The printing machine 40 which is herein disclosed is fully illustrated and described in my copending application, Serial No. 388,998, filed April 17, 1941, and hence the printing machine will be described herein only insofar as the particular mechanisms thereof are directly related to the operation or functioning of the lister 41.

In the use of the lister 41 the paper holder 42 is located in its most forward or loading position of Fig. 1 at the time when a form F is clamped therein, and as an incident to the first cycle of the operation of the printing machine 40 the paper holder 42 is actuated in a rearward direction in an amount sufficient to properly position the upper line or section of the form F opposite the printing position, as illustrated in Fig. 2 of the drawings, so that during the latter portion of this operation of the machine, a printing impression is made upon the upper line or section of the form F. In successive cycles of operation of the printing machine the form F is similarly advanced in a direction rearwardly of the machine to successive intermediate positions to thereby bring successive lines or sections of the form F into alignment with the printing position, and when the lister has reached its last or terminal position and the printing impression in the last line or section of the form F has been completed, the lister 41 operates automatically to return the paper holder

42 and the completed form in a direction forwardly of the machine so that the paper holder 42 is located in its most forward or loading position, and in the form of the invention shown in Figs. 2 and 23 to 28, the paper clamps are automatically released as the paper holder reaches its loading position, thereby to facilitate reloading of the paper holder.

The printing devices

The printing devices D may be of many different types, and the characteristics of the printing devices must of course be related in every instance to the construction and operational characteristics of the printing machine. For use with the printing machine 40 herein shown a printing device of the character disclosed for example in Gollwitzer Patent No. 2,132,412, patented October 11, 1938, may be employed. In other instances, where a different construction and arrangement is provided in a printing machine, a different type of printing device such as that shown in Gollwitzer Patent No. 1,992,661, patented February 26, 1935, may be employed. In other instances the present invention may also be employed with printing machines which utilize printing devices of the stencil type wherein a thin sheet of stencil paper is incorporated in a protective carrier or frame. Since printing devices of the various types above mentioned are well known in the art, no specific description or illustration thereof will be incorporated herein. It may be observed, however, that such printing devices are in many instances classified into a relatively large number of groups or classes, and such classification may be attained through the use of suitable identifying means at selected identifying positions on the printing devices. In the present instances the printing devices may bear one or more identifying tabs 65 disposed at selected positions along their upper edges in the general manner disclosed in the aforesaid Gollwitzer Patent No. 2,142,412, and it will be observed that while a relatively large number of identifying positions are available along the upper edge of each printing device, there is but a single tab 65 illustrated in Fig. 2 of the drawings.

The sheet or form

The lister of the present invention may be employed for listing operations with forms having a variety of different line spacing arrangements or dimensions. A manifold arrangement of a plurality of sheets and carbon paper may, of course, be used, and such a manifold arrangement is contemplated as being generically included where reference is hereinafter made to a sheet or form. In the particular embodiment illustrated herein the lister is adapted for use in producing checks 66 which are afforded by separable parts, or sections of the sheet or form F. The several checks afforded in the sheet or form F are in the present case joined by perforated lines 67, and the spacing 68 of the lines 67 constitutes what may be termed the line spacing dimension of the form F. Where the lister 41 is employed in the production of checks 66 or the like the printing devices D usually carry type matter which prints the name of the payee as well as the amount of the check in words and figures, and in addition, a check number, the date, and the signature may be printed simultaneously at 69, 70 and 71, respectively, through the use of auxiliary printing means governed by

5 a control plunger 72 in a known manner. The number of checks 66 included in a sheet or form F may vary, of course, and in the lister herein disclosed, the mechanism is constructed and arranged to handle forms F including five checks 66 of the dimensions illustrated.

The printing machine

10 The printing machine herein illustrated is of the type wherein the impression means is provided by a platen mechanism P, and this platen mechanism is supported in an operative relationship above the table top T by a rigid printing frame 125, the specific construction of which is illustrated and described in my Patent No. 2,275,439, patented March 10, 1942. The printing frame 125 is in the present case disposed so as to project upwardly from the table top T at a point located at a considerable distance rearwardly and to the right of the printing position, and the printing frame extends forwardly at an angle of substantially 45 degrees with respect to the forward edge 43' of the printing machine frame 43, thereby to locate a head 130, fixed on the forward end of the printing frame, directly over the printing position. The magazine M is located just to the right of the vertically extending portion 125' of the printing frame 125 and the printing devices B are advanced from the bottom of the magazine M in a forward direction and then along a suitable guide path beneath the table top T to the printing position. The particular arrangement of the advancing path is disclosed in my aforesaid copending application, Serial No. 398,988. The advancing means of the printing machine are arranged to advance the printing devices in a step by step manner such that each printing device comes at rest at a plurality of different stations along 15 the printing device guideway, and in the present machine the first of these stations constitutes a sensing station at which suitable identifying means such as tabs 65 may be sensed to determine whether or not each printing device carries such a tab at one or more selected identifying positions thereon. The sensed presence or absence of such a tab when the printing device is at sensing station may be rendered operative 20 to control subsequent operations of the machine, and particularly may be rendered active to control the operation of the platen mechanism P when the printing device from which the sensed indication is derived reaches printing position. The selector mechanism whereby such 25 controlling action is attained is but fragmentally shown in the present drawings wherein a control plunger 126 is shown on the front panel of the machine for rendering the selector mechanism active or inactive as desired. Further details of the construction and operation of the selector mechanism may be had by reference to my copending application, Serial No. 392,151 filed 30 May 6, 1941.

35 The platen mechanism P is herein illustrated as being of the form which is utilized in the printing machine shown in my copending application Serial No. 388,988, and in my aforesaid Patent No. 2,275,439, and this platen mechanism is described in detail in my copending application, Serial No. 361,530, filed October 17, 1940. The platen mechanism P comprises a carriage C supported for reciprocation in a direction from front to rear of the printing machine along a guideway provided by a guide plate 130' mounted beneath the head 130 of the printing frame 125, and the

platen roller PR is supported on and carried by the carriage C. The platen roller PR is arranged in a horizontal position at right angles to the path of reciprocation of the carriage C, that is, parallel to the forward edge 43' of the printing machine frame. The platen roller PR is supported by means such as toggles 131 so that the platen roller may be shifted from a normal elevated or inactive position wherein the platen roller may be effective to press a sheet or form F into printing cooperation with a printing device D disposed at printing position.

The platen mechanism P, in the form disclosed, is arranged so that the platen roller is in its elevated or inactive position when the carriage C is in its rearward or at rest position shown in Figs. 1 and 3 of the drawings. When a printing operation is to be performed the carriage C is actuated in a forward direction through an idle stroke, and in the course of such forward movement of the carriage C the toggle means 131 are actuated to shift the platen roller PR to its lower or active position. The platen roller PR reaches its lower or active position at substantially the time when the forward structure of the carriage C has been completed and the toggle means are then latched so as to maintain the platen roller in its lower or active position during the return or rearward stroke of the carriage C. Hence during the rearward or active stroke of the carriage C the platen roller PR may be rolled across the sheet or form to effect the desired printing operation. As the platen roller PR approaches the rear end of its stroke and has completed the desired printing operation, it is withdrawn to its elevated or inactive position so that the sheet or form may be readily shifted, or removed and replaced.

The actuating means for the carriage C is described in detail in my aforesaid copending application, Serial No. 361,530, and for present purposes it is sufficient only to point out that this actuating means includes a horizontal rock shaft 132 mounted in the printing frame 125 rearwardly of the head 130 thereof and parallel to the forward edge 43'. The rock shaft 132 has an arm 133 fixed on one of its ends, and a vertically extending operating link 134 extends upwardly from beneath the table top T and is connected to the arm 133 so that through vertical reciprocation of the actuating link 134 a rocking movement may be imparted to the shaft 132. At its other end the rock shaft 132 has a downwardly projecting arm 135 fixed thereto and this arm 135 is operatively connected to the carriage C by a pair of actuating links 136. At the end of a machine cycle the arm 135 is located in the position shown in Figs. 1 and 3, and when the platen mechanism P is to be driven through an operative printing cycle, the shaft 132 is first rocked in a counterclockwise direction so that the lower end of the arm 135 to which the links 136 are connected is moved in a direction forwardly of the printing machine, thereby to actuate the carriage C in a forward direction through the inactive portion of its cycle. The rocking movement of the shaft 132 is then reversed so that the shaft rocks in a clockwise direction thereby to withdraw the carriage C in a rearward direction through its active or printing stroke.

In normal use of the printing machine 40 the various operative cycles of the machine are normally initiated by selective manipulation of control means such as a plurality of foot pedals 140,

141 and 142, Fig. 1, which are disposed near the floor beneath the printing machine frame 43. The pedals 140, 141 and 142 are disposed in or adjacent to the knee-hole opening of the desk-like frame 43 so as to be conveniently accessible for manipulation by an operator seated immediately in front of the forward edge 43' of the printing machine frame. The foot pedals 140, 141 and 142 are rendered active selectively to 10 initiate the desired machine cycle by momentary depression of the selected foot pedal, and when thus actuated may serve to initiate different types of single cycle operations of the various actuating means which are embodied in the printing machine. These actuating means are fully described in my aforesaid copending application Serial No. 388,988, and reference may be had to this copending application for details of construction and operation of the actuating and control means of 15 the printing machine. For present purposes it is sufficient to point out that the printing machine 40 is driven by a motor 145, shown diagrammatically in Fig. 4, which is energized through a switch 146 controlled by a plunger 147 located in 20 the forward or control panel of the printing machine as shown in Fig. 1. The drive motor 145 operates through suitable speed reducing means to drive the main actuating element (not shown) of the machine, and when any portion or mechanism 25 of the machine is to be driven through an operating cycle, this main drive element is connected to a normal stationary drive shaft to rotate the drive shaft through a single revolution. When the drive shaft is thus being rotated it 30 may be connected so as to drive the printing device advancing means or the platen mechanism P, or both, and such selective connection is governed by the foot pedals 140, 141 and 142. The foot pedal 140 serves to cause single cycle operation 35 of the printing device advancing means, and since such operation of the printing device advancing means may take place without operation of the platen mechanism P, this foot pedal 140 is often termed the skip pedal of the machine. 40 The foot pedal 141 serves to cause operation of the platen mechanism P and since such operation of the platen mechanism may take place without operation of the printing device advancing means, the foot pedal 141 is often termed the repeat 45 pedal. It will be understood that the actuation 50 of the various foot pedals is momentary in character since it is necessary to allow the foot pedals to return to their normal positions in order to terminate operation of the machine at the end 55 of one cycle.

The foot pedal 142 is arranged, when momentarily depressed, to cause simultaneous or timed operation of the printing device advancing means and of the platen mechanism P, and since such 60 operation results in the performance of but a single printing impression from each printing device D, the foot pedal 142 is usually termed the consecutive pedal of the printing machine. The term "consecutive" as applied to the foot pedal 142 is however merely a term of convenience, since 65 the printing machine 40 as disclosed in my aforesaid copending application Serial No. 388,998 embodies means whereby the printing device advancing means may be automatically disabled in certain cycles in a predetermined sequence such that a predetermined number of printing impressions may be made from each printing device. Such automatic control mechanism may 70 be termed the multi-print mechanism of the printing machine, and while such mechanism is

not usually employed with a lister of the type to which the present invention pertains, there may be instances where such mechanism may be advantageously used in listing work, and it should therefore be observed that such multi-print mechanism in the printing machine herein disclosed is rendered operative or inoperative under control of a plunger 181 located in the front or control panel of the printing machine frame.

Printing machines of the type disclosed herein often embody means for causing printing of only predetermined or selected parts of the information or type matter carried on each printing device D, and various expedients may be employed to attain each selection. In the printing machine 40 shown in the present drawings this result is attained through selective manipulation of the platen roller PR, and this manipulation is attained automatically as disclosed in detail in my copending application Serial No. 361,530. Such automatic selection or variation of the automatic cut off action of the platen roller PR is usually unnecessary in the listing operations performed by listers of the type to which the present invention pertains, but instances may arise where such action is desirable. In this connection it is to be noted that a plurality of platen faces PF may be provided at angularly spaced locations about the axis of the platen roller PR and the platen faces are of such a size as to effect printing cooperation with the desired portions of the type matter. As disclosed in my aforesaid copending application Serial No. 361,530, the automatic platen mechanism may be rendered active or inactive through adjustment of a control knob 170 which is located on the printing frame rearwardly of the head 130 thereof.

In certain uses of the printing machine 40, such for example as in the use of a listing device such as that to which the present invention pertains, use may also be made of a means which causes continuous operation of the printing machine and which automatically stops operation of the printing machine when certain undesired conditions are detected. Such means may be termed the auto-stop mechanism of the printing machine, and this auto-stop mechanism is fully disclosed in my aforesaid copending application Serial No. 388,998. Since reference may be had to said copending application for details of construction and operation of the auto-stop mechanism, it will suffice for present purposes to point out that the auto-stop mechanism is under control of a plunger 180 mounted in the front panel of the printing machine, and, when the control plunger 180 is withdrawn in an outward direction, means is effective to actuate the mechanism associated with the consecutive pedal 142. Thus the platen mechanism and printing device advancing mechanism will, in the absence of a dominating controlling action of the selector mechanism, operate continuously so long as the auto-stop plunger 180 is retained in its outer or withdrawn position. The auto-stop mechanism, as described in the aforesaid copending application Serial No. 388,998, embodies means for returning the auto-stop member 180 to its inward position, thereby to terminate the continuous operation of the printing machine.

As shown in Fig. 4 of the drawings, this means comprises a solenoid 181 arranged to be energized whenever an undesired operating condition is detected by any one of a plurality of detecting means which may be provided in the machine. When the solenoid 181 is thus energized the con-

trol plunger 180 is moved to its inner position. Thus, wires 183 and 184 and an intermediate conditioning switch 185 serve to connect one terminal of the solenoid 181 to one side of the motor circuit between the motor 145 and the motor switch 146. The other side of the motor circuit is connected by a wire 186 to one terminal of a control switch 187, the other terminal of the switch 187 being connected by a wire 188 to the other terminal of the solenoid 181. The control switch 187, may, of course, be governed by any desired detecting means, but as herein shown this switch is governed by a detecting finger 189. The detecting finger 189, as disclosed in detail in my aforesaid copending application Serial No. 388,998, is arranged as a detecting means associated with the magazine M, and in each cycle of operation of the printing device feeding means the finger 189 moves into contact with the edge of the lower printing device in the magazine M. The switch 187 is a normally open switch and when the detecting finger 189 engages a printing device in the magazine M, it is ineffective to close the switch 187. When, however, the last printing device has been withdrawn from the magazine M, the detecting finger 189 closes the switch 187 and thereby energizes the solenoid 181 and cause the auto-stop mechanism to stop the machine. The continuous operation of the printing machine under the control of the auto-stop means may, in many instances, be modified through the dominating action of the selector mechanism, as disclosed in my aforesaid copending application Serial No. 392,151. Thus when the selector mechanism is operative there will be certain cycles of operation of the printing machine wherein the platen mechanism will remain inactive. Hence while the printing machine will maintain its continuous operation under such circumstances, certain printing devices D will be skipped. The auto-stop mechanism, as will hereinafter be described in detail, is utilized under the present invention to cause automatic stopping of the printing machine when the printing of a Form F has been completed.

The listing mechanism

The lister 41 of the present invention includes a main housing 200 mounted on the rear wall 201 of the printing machine 40 directly rearwardly of the printing position, and the main housing 200 has a guideway member 202 associated therewith so as to rest upon the table top T and extend therealong toward the printing position to act as a guide for the movements of the paper holder 42. The actuating mechanism for attaining the desired movements of the paper holder is, in the present instance, enclosed mainly within the housing 200 and is operatively connected to the paper holder 42 by means such as a flexible rack 203 which extends along the guideway 202. The actuating mechanism of the lister 40 is driven from the drive means of the platen mechanism P so as to be operated in timed relation to the operation of the platen. As shown in Figs. 1 and 3 of the drawings, this driving action is effected by a drive link 205 connected at its rear end to an upwardly projecting operating lever 206 of the lister actuating mechanism and operatively associated at its forward end with the actuating arm 135 of the platen mechanism. As shown in Figs. 3 and 20 such connection of the forward end of the link 205 is provided by a headed stud 207 which is extended through a longitudinal slot 208 in the

forward portion of the link 205. The arrangement is such that as the actuating arm 135 moves forwardly to operate the platen mechanism through its idle or forward stroke, the stud 207 acts against the forward end of the slot 208 so that the link 205 is also drawn forwardly to rock the lever 206 in a forward direction, and the mechanism enclosed within the housing 200 is thereby operated to shift the rack 203 in a rearward direction. Such shifting movement of the rack 203 is accurately controlled so that for each operation of the platen mechanism P the paper holder 42 is advanced in a rearward direction through the desired line spacing movement. When the operator wishes to impart a similar line spacing movement to the paper holder 42 without operation of the platen mechanism P, a handle 209 on the forward end of the link 205 may be grasped and the link may be manually withdrawn in a forward direction. The length of the slot 208 is such that it limits such manual movement to a stroke which is the same as the stroke imparted to the link 205 by the arm 135, and hence an accurate line spacing movement of the paper holder may be attained manually.

The paper holder 42, as herein shown, comprises a mounting arm 210 adapted to overlie the top of the guideway 202, and a cross frame 211 extends at right angles from the mounting arm 210. The cross frame 211 has spaced paper clamps 212 thereon which project in a forward direction and are adapted to engage a bordering edge of a sheet of paper to clamp the sheet to the paper holder. The form of the guideway 202 is such as to facilitate mounting and guiding of the mounting arm 210 thereon, and as shown in Fig. 9 of the drawings, the guideway 202 comprises a bottom plate 215 having a spacer plate 216 secured along each of the outer edges of its upper face, and flange plates 217 are secured on the tops of the spacer plates 216 so as to project toward each other beyond the spacer plates 216 and thereby define inwardly facing grooves 218 beneath the flange plates 217. The mounting arm 210 has a plurality of flanged rollers 219, Figs. 23 and 28, mounted on its lower face and these rollers 219 are arranged so that the flanges thereof engage in the grooves 218 to hold the mounting arm 210 and the paper holder 42 in a predetermined relation to the guideway 202 as the paper holder is advanced along the guideway. As shown in Figs. 23 and 28, three rollers 219 are employed, and the central one of these rollers is mounted on a spring biased arm 219' which holds this roller 219 against one side of the guideway 202 and maintains the other two rollers in contact with the other side of the guideway. The connection between the mounting arm 210 of the paper holder and the flexible rack 205 is preferably releasable in character, and for this purpose an upstanding stud 220 is provided on the forward end of the flexible rack 205 in a position to engage with a complementary opening formed in the rear end of the mounting arm 210.

The paper clamps 212 each comprise a pair of jaws mounted for rocking movement on a shaft 211' mounted on the cross member 211 as shown in Figs. 23 to 28. A spring 212' acting between the rearwardly projecting ends of the jaws urges the forward ends of the jaws together so that a sheet or form F may be clamped therebetween. The rear end of the lower jaw rests on an in-turned flange 211'' of the cross member, and when the jaws are to be released, a cam shaft 212'' mounted on the cross member 211 is rocked

in a counter-clockwise direction from the position shown in Fig. 24, to press the rear end of the upper jaw downwardly and thereby raise the forward end of the upper jaw to its released or open position. The cam shaft 212'' may be operated manually to clamp and unclamp the paper, or in accordance with the present invention the unclamping action may be attained automatically. In the embodiment of the invention shown in Fig. 1 the unclamping is attained manually, and to this end the cam shaft 212'' has an operating arm 221 fixed thereto which may be pressed rearwardly and downwardly to unclamp the paper clamps 212, and the arm 221 remains in its depressed position and the clamps 212 remain unclamped until another arm 222 on the cam shaft is pressed forwardly and downwardly to return the cam to its original position and cause clamping of the paper clamps 212. The clamps 212 are adjustable along the cross member 211, thereby to facilitate the clamping of sheets of varying widths on the paper holder, and this construction is described in detail in my copending application, Serial No. 410,097 filed September 8, 1941. The proper positioning of a sheet or form F in the paper clamps 212 is preferably facilitated by a paper guide 223 fixed on a mounting bar 224 extending along the forward edge 43' of the printing machine frame. The paper guide 223 extends rearwardly along the table top T to an extent sufficient to act as a guide against which the edge of the sheet may be pressed in the course of a sheet mounting operation. The means for automatically releasing the clamps 212 are illustrated in Figs. 2 and 23 to 27, and such automatic means will be described in detail upon completion of the description of the other features of structure and operation of the lister.

The main housing 200 of the lister 41 is formed from a pair of vertically positioned side frames 230 and 231 which are plate-like in character and are flanged toward each other about their edges. A removable cover plate 231 extends between the rear flanges and a portion of the upper flanges of the side frames 230 and 231, thereby to cooperate with the side frames in affording a housing. The two side frames 230 and 231 are connected into a rigid assembly by a plurality of connecting shafts or rods which serve not only to space the two side frames 230 and 231 apart but also to support various operative mechanisms within the housing. Thus, as shown in Fig. 3 of the drawings, three transverse shafts 232, 233 and 234 are disposed at spaced points along and adjacent to the upper edges of the side frames, and the ends of these shafts extend through appropriate openings as 235 in the side frames so that the screw threaded outer ends of the shafts extend into enlarged cylindrical sockets 236 formed about the outer ends of the openings 235. Cylindrical nuts 237 are threaded onto the ends of the shafts 232, 233 and 234 within the sockets 236 to draw the side frames vertically against spacing means such as spacing sleeves associated with or formed on the cross shafts. Adjacent to the lower edge of the housing three transverse or cross shafts 242, 243 and 244 are similarly extended between two side frames 230 and 231, and intermediate the upper and lower edges another shaft 245 is also mounted in a similar manner.

The rigid housing assembly which is thus provided is mounted on the rear wall 201 of the printing machine frame, and for this purpose the side frames 230 and 231 have oppositely extend-

ing mounting feet 248 and 249 formed thereon near the lower edges of the side frame members. The mounting feet 248 and 249 have forwardly projecting flanges 248' and 249' which are arranged to rest upon the upper edge of a horizontal mounting bar 250 fixed to the rear surface of the rear wall 201. Spaced upwardly from the mounting foot 249 the side frame 231 has a headed stud 251 which is threaded in a horizontal position into the forward edge of the side frame 231. The head 252 of the stud 251 is adapted to be extended through the enlarged end of a horizontal locating keyhole slot 253, after which the entire lister housing 200 is moved in a right hand direction with respect to the machine, or in other words in an upward direction as shown in Fig. 6 of the drawings, to thereby interlock the head 252 with the narrow portion of the slot 253. A knurled nut 254 positioned on the threaded stud 251 may then be tightened against the outer or rear face of the rear wall 201. The relation of the head 252 to the lister housing 200 may be adjusted by rotation of the screw threaded stud 251 and such adjustment may be preserved by a lock knot 255 mounted on the stud 251 and adapted to be drawn into firm engagement with the rear edge of the side frame 231. During the movements required to engage the stud 251 with the key hole slot 253 the major portion of the weight of the lister housing 200 may be supported by resting the flanges 248' and 249' on the mounting bar 250. After the engagement of the stud 251 with the key hole slot 253 has been completed, securing screws 258 carried permanently in the mounting feet 248 and 249 may be screwed into threaded openings 259 formed at appropriate positions in the mounting bar 250.

The adjustment of the length or relation of the stud 251 is utilized to locate the housing 200 in such a position that the guide member 202 will be parallel to and rest upon the table top T. The guide member 202 is preferably detachably related to the house 200 and such a connection is afforded by a mounting plate 260 which, as shown in Figs. 5, 7, 8 and 13, is located in rabbeted grooves 261 formed in the inturned flanges which are formed along the upper edges of the side frames 230 and 231. The mounting plate 260 is held in position by screws 262 and the plate extends from the forward ends of the two side frames for a substantial distance rearwardly therealong, so that the rear edge of the mounting plate 260 is disposed just forwardly and downwardly of the forward edge of the cover plate 231', as shown in Fig. 5. The mounting plate 260 has a pair of upstanding parallel guide ribs 263 which are so spaced from each other that the guide member 202 may be fitted snugly therebetween. Near the rear ends of the ribs 263 enlarged bosses 264 are provided for the formation of vertically positioned screw threaded bores therein, and clamping screws 265 threaded into these bores have clamping flanges 256 thereon which are adapted to engage the upper surfaces of the guide member 202 to clamp the guide member firmly in position in the space between the two ribs 263.

As will be evident in Figs. 7 and 8, the flexible rack 203 is located in the guide member 202 so that the bordering edge portions of the flexible rack are extended into the two grooves 218 of the guide member 202, and thereby the rack 203 is confined in such a manner as to prevent flexure or bending of that portion of the rack 203 which is located within the guide member

202. It will also be evident however that the flexible rack 203 extends rearwardly out of and beyond the rear end of the guide member 202, and actuating means are provided within the housing 200 to impart the desired longitudinal movements to the rack and through the rack to the paper holder 42. In accordance with present invention such movements are imparted to the rack 203 in both directions longitudinally of the rack, and this end is attained through the employment of actuating means which is so connected and related to the flexible rack that the rack may act in tension to advance the paper holder 42 in a rearward advancing or line spacing direction or may act in compression to actuate the paper holder forwardly of the printing machine to return the paper holder to its loading position. In attaining this result the rack 203 is extended from the rear end of the guide member 202 and into operative engagement with a sprocket 270 which is mounted in fixed relation upon a rotatable cross shaft 271 journaled in the side frames 230 and 231. The sprocket 270 is so formed and positioned that its teeth 272 may engage spaced openings 273 formed in a longitudinal row in the flexible rack 203 adjacent to one side edge thereof. Such engagement of the openings 273 of the rack 203 with the teeth 272 of the sprocket is governed by guide means which engage bordering edges of the upper and lower faces of the rack 203 rearwardly of the rear end of the guideway 202 to thereby confine and guide the rack 203 in a manner similar to the guiding action of the grooves 218 of the guide member 202. To this end a pair of guide disks 275 are mounted in coaxial relation with the sprocket 270 and on opposite sides of the sprocket in such a relation that the bordering edges of the lower face of the rack 203 may be engaged with the two disks 275, and guide plates 276 which are generally crescent shaped, as shown in Fig. 8, are disposed adjacent to the outer or remote sides of the disks 275 so that inturned bordering flanges 277 formed along the upper or outer edges of the guide plates 276 may, at least at certain points therealong, engage with the bordering edges of the upper face of the flexible rack 203. The desired stationary mounting for the crescent shaped plates 276 is afforded by the cross shafts 233 and 243 which extend through the plates 276 adjacent the opposite ends thereof, spacing means, such as the spacing sleeves 278 and 279 shown in Fig. 6 as being mounted on the shaft 233, being provided on both 55 of the supporting shafts 233 and 243 to hold the plates 276 in position thereon. Thus the outer edges of the guide disks 275 and the flanges 277 of the guide plates 276 cooperate to guide the flexible rack 203 and maintain the same in engagement with the teeth 272 of the rack at a predetermined radial distance from the axis of the sprocket 270.

The sprocket 270 and the two guide disks 275 are, together with other elements which will hereinafter be described, mounted in a non-rotative relationship to each other upon a sleeve 280. The sleeve 280 has a flange 281 at its left hand end, as shown in Fig. 12, and the several elements carried thereby, including the sprocket 270 and the two disks 275, are held in the desired spaced relation along with the balance of the sleeve 280 by spacer members 282. The elements which are thus arranged on the sleeve 280 are held in the desired assembled relation 75 ship on the sleeve 280 by a plurality of tie rods

284 which extend through these elements and through the flange 281 of the sleeve; and the sleeve 280 is secured in a non-rotative relationship upon the shaft 271 by a plurality of pins 285.

When the paper holder 42 is to be moved through a line spacing movement in a rearward advancing direction, the power or actuating force is applied directly through the flexible rack 203, since by this arrangement the flexible rack may be constructed so as to govern the length of each of such line spacing movements. Thus the flexible rack 203 may constitute the only element which requires replacement when a different line spacing movement is desired. To this end the flexible rack 203, as shown in Fig. 22 of the drawings, is formed with a plurality of openings 290 spaced longitudinally thereof in amounts which are equal to the desired line spacing movements. Thus the line spacing dimension is indicated at 291 in Fig. 22. The openings 290 are located in that area of the flexible rack which is between the row of openings 273 and the most remote side edge of the rack, and since the openings 290 are intended to be engaged by an actuating pawl mechanism, these openings are preferably arranged alternately in two rows as will be evident in Fig. 22.

The actuating pawl mechanism which is engageable with the openings 290 of the flexible rack is, in the present instance, driven by the actuating lever 206, as will hereinafter be described in detail, and the pawl mechanism includes a rocker arm 300 extending radially from a mounting sleeve 201 carried on the shaft 271 just to the right of the sleeve 280, as shown in Fig. 12 of the drawings. The rocker arm 300 has a mounting head 302 which extends to the left, as viewed in Fig. 12, from the outer end of the arm, and at its left hand end the head 302 is flanged radially inwardly at 303 so that a pawl-mounting shaft 304 may extend from the flange 303 to the arm 300 parallel to the shaft 271. The mounting shaft 304 has a pair of pawls 305 mounted thereon so that the ends thereof may be engaged with the openings 290 of the flexible rack to impart rearward or advancing movement to the rack and the paper holder, and coil springs 306 acting between the head 302 and the pawls 305 urge the pawls 305 toward such engagement.

The actuating lever 206 is mounted for rocking movement on the cross shaft 232, and this lever is in the nature of a bell crank having an arm 310 which extends generally horizontally and in a forward direction when the lever 206 is in its at rest position of Fig. 5. A link 311 has one of its ends pivoted at 312 to the end of arm 310, and the other end of the link 311 is pivoted at 313 to the pawl-carrying rocker arm 300. The parts of this drive mechanism are urged to the normal or at rest relationship shown in Fig. 5 by a coil spring 314 which acts between the cross shaft 242 and a spring anchor 315 fixed on a downwardly projecting arm 316 of the lever 206.

It will be observed that the normal or at rest position of the lever 206, Figs. 3 and 5, is attained when the actuating arm 135 of the platen mechanism P returns in a rearward direction to its at rest position shown in Fig. 3, and which position is assumed at the end of a cycle of operation of the platen mechanism. When a new cycle of operation of the platen mechanism P is initiated the arm 135 rocks in a counter-clockwise direction so as to withdraw the actuating link 205 in a forward direction. The lever 206 is thereby rocked from the position shown in Fig. 5 toward

the position shown in Fig. 14, and it will be observed that during such movement the arm 310 and the link 311 act as a toggle. Hence the maximum stroke which may be applied to the pawl carrying arm 300 is determined by the toggle 310-311, for although in some instances the toggle may move through and beyond its fully extended position, the maximum throw of the pawl carrying arm 300 will in such instances remain unchanged. The end of the actuating link 205 is associated with the lever 206 by means including a stud 320 which may be adjustably fixed in different positions along a slot 321 formed in the lever 206. The stud 320 is left in position 15 in the lever 206 when the link 205 is to be disconnected from the printing machine, the operative relationship being established by means of a downwardly facing slot 322 formed in the link 205 so as to be adapted to be engaged or hooked 20 over the stud 320. A detent spring 323 carried on the link 205 engages the stud 320 to maintain the slot 322 in engagement with the stud.

The adjustment of the stud 320 along the slot 321 determines the initial or at rest position of 25 the lever 206, and consequently this adjustment also determines the at rest position of the pawl carrier 300. In the event that such adjustment of the stud 320 causes the stroke of the link 205 to actuate the toggle 310-311 through and beyond its fully extended position, it will be evident that such movement beyond the fully extended position is ineffective to cause undesired advancing movement of the flexible rack and the paper holder.

35 When the pawl carrier 300 is in its at rest position shown in Figs. 5, 8 and 12 it is desirable that the pawls 305 be rendered inactive, thereby to permit movement of the flexible rack in a reverse or return direction. This end is attained 40 through the provision of a shield carrier 330 mounted on a sleeve 331 which is carried on the shaft 271 between the sleeve 280 and the side frame 230. The shield carrier 330 is flanged at 332 so as to extend to the right as shown in Fig. 45 12 to a point such that a shield 333 carried on the shield carrier 330 may be located between the pawls 305 and the flexible rack 203. The shield carrier 330 is arranged for adjustment about the 50 axis of the shaft 271 to a position wherein the shield 333 will underlie and disable the pawls 305 when the pawl carrier 300 is in its at rest position. The shield carrier 330 is held in such an 55 adjusted position by a stud 334 which projects therefrom through an arcuate slot 335 in the side frame 230 and which has a clamp nut 336 threaded on its outer end.

The adjustment of the shield carrier 330 is utilized in facilitating the adjustment of the stud 320, and this end is attained by the provision of 60 a downwardly extending ear 337 formed on the flange 303 of the pawl carrier 300. This ear 337 is arranged to engage with a surface 338 formed on the portion 332 of the shield carrier 330. 65 With this arrangement the shield carrier 330 may, while the link 205 is disconnected, be adjusted in a counterclockwise direction as shown in Figs. 5 and 8 until the left hand edge of the shield 333 is relatively close to the normal at rest 70 location of an opening 290 of the flexible rack 203, and in such movement of the shield carrier 330 the edge 338 of the shield carrier engages the ear 337 of the pawl carrier 300, thereby to 75 similarly move the pawl carrier and maintain the pawls 305 in engagement with the shield 333.

In the course of such adjustment the lever 206 is correspondingly moved, and the proper position of the stud 320 is then determined by fitting the link 205 in its most rearward relation with respect to the actuating arm 125 and then adjusting the stud 320 along the slot 321 until the stud is aligned with the slot 322 of the link 205.

The present invention provides for return of the paper holder 42 by power means, and as herein shown this power means tends constantly to impart such return movement to the paper holder. This tendency of the power return means is, under the present invention, controlled at all times except when a return movement of the paper holder 42 is desired. In the present instance the power return means for imparting such return movement to the paper holder is in the nature of spring means, the tension of which is built up or increased as an incident to the advancing movements which are imparted to the paper holder by the pawl mechanism 300. Thus as shown in Figs. 3 and 12 of the drawings, a spring mechanism 340 is associated with the shaft 271 and this spring mechanism tends to impart rotative movement to the shaft 271 in a clockwise direction as viewed in Fig. 8. Thus the spring mechanism 340 is tensioned each time the pawl carrier 300 operates through a line spacing movement. In this connection it will be observed that when the pawls 305 engage an opening 290 in the flexible rack so as to impart an advancing movement thereto, the engagement of the openings 273 of the rack 203 with the sprocket 270 causes the shaft 271 to be rotated in a counterclockwise direction as viewed in Figs. 3 and 8. The spring mechanism 340 as herein shown comprises a helically wound band 341 of spring steel having its inner end secured by a screw 342 to a hub 343 which is in turn fixed upon a sleeve 344. The sleeve 344 has an end flange 345, and the sleeve 344 is positioned on the reduced end portion 346 of the shaft 271 which projects beyond the side frame 231. A set screw 347 passes through the flange 345 to retain the sleeve in any desired rotative relation to the shaft 271. The other or outer end of the spring 341 is stationarily connected to the side frame 231 by an anchor stud 348, as shown in Figs. 3 and 6 of the drawings. A pair of guide disks 349 and 350 are provided on opposite faces of the spring 341, the disk 349 being clamped between the flange 345 and the hub 343 while the disk 350 is held in position between a shoulder 351 on the shaft 271 and the adjacent end of the sleeve 344.

The constant biasing action of the spring mechanism 340 is, in the present instance, controlled by a one-way retaining mechanism which is preferably in the nature of a friction retaining means, thereby to enable the controlling action to be accurately governed. Thus as shown in Figs. 12 and 14 to 19, a retaining mechanism 360 is mounted on the cross shaft 243, and this retaining mechanism is connected to the shaft 271 by a pinion 361 connected to one element of the retaining mechanism 360 and meshed with a gear 362 which is fixed on the sleeve 280 by the tie rods 284 and the associated spacer means. The retaining mechanism 360 is so constructed and arranged that when it is engaged or operated it acts to prevent forward or return movement of the paper holder 42. When, however, the retaining mechanism 360 is released, the spring mechanism 340 is rendered

effective and the sprocket 270 is rotated in a clockwise direction as viewed in Fig. 8 to impart rapid return movement to the paper holder. It is essential that such rapid return movement be terminated when the paper holder 42 has reached its initial or loading position, and for this purpose stop means are associated with the shaft 271. These stop means in the form herein disclosed comprise a stop segment 370 rotatably mounted on the cross shaft 245 and having segmentally arranged gear teeth 371 formed thereon so as to mesh with a pinion 373 fixed on the sleeve 280 by the tie rods 284 between the sprocket 270 and the gear 362. The gear ratio between the pinion 373 and the segmentally arranged gear teeth 371 is such that in the rotative movements of the sprocket 270 required to move the paper holder 42 throughout its entire range, the stop segment 370 will move through but a portion of one revolution. Thus when the paper holder 42 is in its loading position, the stop segment 370 will occupy the position shown in Fig. 8 of the drawings wherein an abutment edge 375 formed on the stop segment 370 is in abutment with a stop member 376. When advancing movements are imparted to the paper holder 42 by actuation of the flexible rack 203, resulting rotative movement of the sprocket 270 causes the stop segment 370 to be rotated in a clockwise direction from the position shown in Fig. 8 to and through position shown in Fig. 14, and in some instances the stop segment 370 may move to the position shown in Figs. 15 and 16. When such advancing movements are terminated the retaining mechanism 360 acts to retain the sprocket 270 and the stop segment 370 in the positions to which they have thus been moved. When the retaining mechanism 360 is released, however, the spring mechanism 340 acts upon the shaft 271 to impart return movement to the paper holder in a forward direction, and as such return movement progresses the stop segment 370 returns in a counterclockwise direction until the abutment surface 375 strikes the abutment member 376. When this takes place the paper holder 42 is located in its loading position shown in Fig. 3 of the drawings; and moreover, it is to be observed that at this time one or more of the openings 273 in the flexible rack 203 remain in engagement with the teeth 272 of the sprocket 270, as shown in Fig. 8. The arrangement is such, however, that the operator desires to release the flexible rack 203 from the sprocket 270, the stop member 376 may be manipulated so as to permit further clockwise movement of the sprocket 270. Such further movement discharges the rear end of the flexible rack 203 in a forward direction to thereby release all of the openings 273 from the sprocket. In accordance with the present invention this result is attained through formation of two different abutment surfaces on the stop member 376, one of which is arranged to determine the extent of the return movement of the sprocket 270 during normal operation and the other of which permits the added rotative movement of the sprocket which is required to release the rack 203 from the sprocket. In the form herein shown this end is attained by forming the stop member 376 as a bar of rectangular cross section having trunnions 377 and 378 extending from the opposite ends thereof and eccentrically located with respect to the longitudinal axis of the rectangular bar. The trunnions 377 and 378 are journaled

in the side frames 230 and 231 and the trunnion 378 extends through the side frame 231 and has an operating lever 379 fixed thereon by means such as a set screw 380. A spring 381 acting between the stop member 376 and the cross shaft 244 tends to impart counterclockwise rotation to the stop member 376, as viewed in Fig. 8 of the drawings, and such counterclockwise rotation is limited by engagement of the operating handle 379 with a stop pin 383, Fig. 3, fixed in the side frame 231. When the stop member 376 is thus positioned as shown in Fig. 8 of the drawings, the abutment edge 375 of the stop segment 370 engages a spring 384 mounted on the side of the stop member 376 which is most remote from the mounting axis provided by the trunnions 377 and 378. The spring 384 serves to cushion the stopping action which is imparted to the stop segment 370. When the stop segment 370 engages the spring 384 to terminate the return movement which is to be imparted to the paper holder 242, the paper holder is stopped in its normal loading position. When, however, the operator wishes to disconnect the rack 203 from the sprocket 270, the handle 379 is rocked in a clockwise direction as viewed in Figs. 3, 8 and 11 until the handle 379 strikes a stop pin 386, Fig. 3, thereby to locate the stop member 376 in the position shown in Fig. 11. The stop shoulder 375 of the stop segment 370 may then move into abutment with a side surface 387 of the stop member 376, as shown in Fig. 11, thereby to permit counterclockwise movement of the stop segment 370 through a substantial distance beyond the position in which it is normally stopped. This additional movement allows the sprocket 270 to move through an additional distance in a clockwise direction, Fig. 8, thereby to release the flexible rack 203 from the teeth of the sprocket. When the flexible rack has thus been released, the stop member 376 remains in the position shown in Fig. 11, it being observed that the spring 381 is at this time under considerable tension so as to tend to return the stop member 376 to its normal position shown in Fig. 8 as soon as movement of the stop segment 370 in a clockwise direction is initiated. Hence when a different flexible rack 203 is introduced into the guideway 202 and is brought into operative association with the sprocket 270, the sprocket 270 may be rotated in a counterclockwise direction until the desired engagement of the flexible rack with the sprocket has been attained, and as an incident to such engagement the stop member 376 returns automatically to its normal position of Fig. 8.

In accordance with the present invention the rack 203 is so formed as to facilitate such operative engagement of the rack with the sprocket 270. In attaining this result a rearwardly facing abutment edge 273' is formed at the rear end of the rack 203 in such a position that it is spaced from the adjacent openings 273 in the same distance as the adjacent openings 273 in the other parts of the rack. Thus when a flexible rack 203 is moved rearwardly through the guideway 202, the rear end of the flexible rack will move into the guideway afforded between the guide disks 275 and the flanges 277 and edge 273' will move into engagement with the uppermost tooth 272 of the sprocket 270. Since the rack 203 is confined throughout its entire length the paper holder 42 may be forced rearwardly and the rack 203, through action of the abutment edge 273', will impart counterclockwise movement

to the sprocket 270. Such rearward movement of the rack 203 may be continued until the resulting movement of the stop segment 370 releases the stop member 376 for return from its position of Fig. 11 to its normal position of Fig. 8. The mechanism, insofar as the engagement of the rack and the sprocket 272 is concerned, is then in condition for operation of the lister.

The retaining mechanism 360 may be of many different types but I prefer to employ a roller type of friction clutch such as that shown in detail in Figs. 17 to 19. As there shown the retaining mechanism 360 includes a rotatable element 390 and a relatively stationary mechanism 391, both of which are mounted on the shaft 243. The rotatable element 390 as herein shown comprises a cup-shaped cage 392 fixed on a sleeve 393 which is formed integrally with the pinion 361. The sleeve 393, at its left hand end as shown in Fig. 17, abuts the end of a sleeve 394 which extends into abutment with the side frame 230. A screw 395 fixes the sleeve 394 against rotation so that a clearance slot 396 in the sleeve may be properly located at all times. Within the cage 392 a non-rotatable member 398 is disposed so that arms 399 thereon may cooperate in positioning a plurality of detent rollers 400. The detent rollers 400 are adapted to move along surfaces 401 under the influence of springs 402 which act between the arms 399 and the rollers 400 to urge the rollers into contact with the inner periphery of the cage 392. Through such an engagement the rollers 400 act as wedges to prevent rotation of the cage 392 in a counterclockwise direction as viewed in Fig. 18. When the retaining mechanism 360 is to be released, a release member 404 is actuated in a clockwise direction as viewed in Fig. 18 so that pins 405 carried on the release member 404 and projecting into the cage 392 are effective to shift the rollers 400 against the action of their springs 402, thereby to release the wedging action of the rollers 400 and permit free movement of the cage 392 in a counterclockwise direction. The release member 404 is mounted for rocking movement about a spacing hub 407 which surrounds the shaft 243 between the stationary member 398 and the side frame 231, and a pin 408 extending from a socket 409 in the side frame 231 and through an opening in the hub 407 passes into a bore 410 in the stationary member 398 to thereby hold the member 398 against rotation.

As the flexible rack is actuated by the pawl mechanism to impart rearward advancing movements to the paper holder, the resulting rotation of the sprocket 270 results in tensioning of the spring mechanism 340. In the course of such tensioning, the cage member 392 of the retaining mechanism 360 is rotated in a clockwise direction as viewed in Fig. 18 and as soon as such advancing movement of the rack 203 is terminated, the springs 402 return the rollers 400 to their active or wedging positions, thereby to maintain the rack 203 and the paper holder 42 in the positions to which they have been moved. In other words, the retaining mechanism 360 acts to prevent the spring mechanism 340 from imparting return movement to the paper holder. When such return movement is to be imparted to the paper holder, the release member 404 is rocked in a clockwise direction, as viewed in Figs. 16 and 18, thereby to cause the pins 405 to release the rollers 400, and this actuation of the release member 404 is attained by a release lever

410 which is fixed on the release member 404 as shown in Figs. 17 and 19.

When the printing machine 40 is first operated after the mounting of a sheet or form therein, the most rear one of the opening 290 will be exposed for engagement by one of the pawls 305, and the pawl mechanism will therefore operate on the flexible rack 203 to shift or advance the paper holder 42 from its loading position to the first printing position or location wherein the upper line or section 66 of the form F will be aligned with the printing position of the printing machine. This first movement of the paper holder from its loading position will in most instances be relatively small, since the loading position of the paper holder need be located forwardly from the first printing location in a distance which is merely sufficient to dispose the second one of the openings 290 beneath the shield 333. In the latter portion of the first machine cycle, the platen mechanism P will operate through its active or printing stroke to print an impression from the printing device at printing position onto the first or upper section 66 of the form F. In the next machine cycle the pawl mechanism engages the second opening 290 of the flexible rack to advance the paper holder 42 to a second position, and a printing impression is made on the second one of the sections 66 of the form F. In succeeding cycles of operations of the machine, the paper holder 42 is shifted to other intermediate positions, and in the last machine cycle which is to be performed with relation to a particular sheet or form, the paper holder is advanced into a terminal position, and after the performance of the printing operation with the paper holder located in the aforesaid terminal position, the paper holder may be returned to its loading position. It will be observed that in each such cycle of operation of the machine the spring mechanism 340 is additionally tensioned so that when the paper holder has reached the aforesaid terminal position, the spring mechanism is under a relatively high tension and is in condition to impart rapid return movement to the paper holder.

It may be desirable of course to impart such return movement to the paper holder from any one of the intermediate positions, as well as from the terminal position, and the present invention enables such return movement to be initiated from any of these positions. The control of the return movement of the paper holder is such that the return movements may be initiated either manually or automatically, the automatic return movement being initiated only after completion of the printing operation on the last one of the sections 66 of the form F. The control mechanism whereby initiation of the return movement of the paper holder is governed, is preferably such that the movements of the paper holder in a return direction may be properly timed with respect to the operating cycles of the printing machine. In addition, the automatic control mechanism which automatically initiates such return movement after the printing operations upon a form F have been completed, is also arranged to govern the auto-stop mechanism of the printing machine to terminate operation of the printing machine when the printing of a form F has been completed.

In attaining such control of the retaining mechanism 360, a retaining mechanism release lever 415 is mounted on a sleeve 416 which is

in turn carried on the sleeve 301. The release lever 415 extends downwardly from the axis of the shaft 271 and has its lower end connected by a link 416 to the clutch release arm 410. 5 The release lever 415 is acted upon by a spring 417 to rock the releasing lever 415 in a counter-clockwise direction. Such rocking movement of the release lever 415 acts through the link 416 to rock the release arm 410 from its full line of position of Fig. 14 to its full line position of Fig. 15, and such movement of the release arm 410 causes the retaining mechanism 360 to be released. The release lever 415 is normally held against such releasing movement by latch means 10 which acts on an upwardly extending ear 418, as shown in Figs. 6 and 7, and this ear 418 is adapted to be engaged and latched by a latch shoulder 420 formed on a rocking latch member 421. The rocking latch member 421 is mounted on a stud 422 which projects from the side frame 231 as shown in Figs. 6 and 7, and a spring 423 acting between the latch member 421 and a spring anchor 424 urges the latch member 421 to its latching position shown in Fig. 14. Thus 15 in order to permit movement of the release lever 415 through a releasing movement, the latch member 421 must be rocked from its active position of Fig. 14 to its inactive or released position of Fig. 15. In attaining the desired timed operation of the release lever 415, the present invention also provides an auxiliary control lever 430 which is pivoted on the axis of the shaft 271 as shown in Fig. 12. The auxiliary control lever 430 is urged in a clockwise direction as viewed 20 in Fig. 14 by a spring 431 acting between the lever 430 and the spring anchor 434. The auxiliary control lever 430 has a laterally projecting ear 431 which, as shown in Figs. 6 and 7, extends across the top of the latch member 421 in a position to abut the ear 418 of the release lever 415. 25 The spring 431 is of such a strength that even when the latch member 421 is released as shown in Fig. 16, the release lever 415 will be held in its inactive position so that the clutch 360 will 30 not be released until the auxiliary control lever 430 is actuated from its position shown in Fig. 16 to its position shown in Fig. 15. Thus it will be clear that the release of the latch 421 serves under such circumstances, merely as a conditioning operation, conditioning the automatic return mechanism for producing return movement of the paper holder 42 when the auxiliary control lever 430 is operated.

The foregoing arrangement of the levers 415, 55 421 and 430 is utilized in obtaining the desired timed operation of the automatic return means, and to this end means is provided in association with the flexible rack 203 for conditioning the control mechanism for release of the retaining mechanism, while means is provided in association with the pawl actuating mechanism for actuating the auxiliary control lever 430 at the end of the cycle of operation of the printing machine. In the accomplishment of the controlling operations as aforesaid, the flexible rack 203 has a control means in the form of an angle bracket 435 fixed thereon in a predetermined relation to the last one of the openings 290, and as the rearward or advancing movement of the flexible rack 203 progresses, the angle member 435 moves rearwardly and strikes a laterally projecting arm 436 formed on a control slide 437. The control slide 437 is mounted for limited sliding movement in a direction from front to rear of the lister housing, and is supported for such 60 65 70 75

movement by the shafts 233 and 234 which have sleeves 279 and 279' thereon, the reduced ends of these sleeves being extended through guide slots 438 formed in the control slide 437. The control slide 437 is urged in a forward direction by a spring 439 acting between an anchoring stud 440 on the slide 437 and a mounting bracket 441 which extends vertically between the shafts 234 and 244. Thus the control slide 437 is normally located in the position shown in Figs. 6 and 7, and it will be observed that the control slide 437 is so mounted that when the control slide 437 is shifted in a rearward direction, its rear end will engage a laterally projecting ear 445 formed on the latch member 421. Such actuation of the control slide 437 takes place when the control bracket 435 moves rearwardly and engages the arm 436 of the control slide. Thus the latch 421 is released as shown in Fig. 16, and this takes place when the paper holder 42 has been moved to its rear or terminal position. It will be understood that the advancing movement of the paper holder 42 takes place in the first half of the cycle of operation of the printing machine 40, and the paper holder 42 must of course be retained in its new position until the desired printing operation has been performed during the last half of the cycle of operation of the printing machine. This is accomplished with the present mechanism since the auxiliary control lever 430 acts through its laterally projecting ear 431 to retain the release lever 415 in the position shown in Fig. 16 after the release of the latch 421.

Means are provided which are operable at the end of the cycle of operation of the printing machine to actuate the auxiliary control lever 430 from the position shown in Fig. 16 to the position shown in Fig. 15, thereby to cause release of the retaining mechanism 360 and initiate the return movement of the paper holder in those instances where the latch 421 has been previously released in the first portion of the machine cycle. These means, as herein shown, are associated with the actuating link 205 and are arranged so that when the link 205 returns in a rearward direction toward its at rest position of Figs. 5 and 15, the auxiliary control lever 430 will be engaged and actuated. To this end a bracket 450 is secured on the side of the link 205, the bracket 450 having a laterally projecting arm 451 thereon at the end of which a rearwardly projecting arm 452 is formed. The rearwardly projecting arm 452 is spaced laterally from the mounting portion of the bracket 450 thereby to define a space or notch 453 within which the upwardly projecting arm portion 421' of the latch member 421 may pass when the link 205 moves into its rearward or at rest position. In such movement the rear end surface 452' of the arm 452 engages the forward edge of the auxiliary control lever 430 to impart the desired actuation to the lever 430. It will be evident that the auxiliary control lever 430 will be actuated by the arm 452 at the end of each cycle of operation of the printing machine, and in all cases except where the paper holder has been moved into its terminal position, the parts will assume the positions and relationship shown in Fig. 5 of the drawings. Thus when the auxiliary control lever is actuated when the paper holder is in an intermediate position, the latch member 421 will serve to retain the release lever 415 in the position shown in Fig. 5. Hence the retaining mechanism 360 will remain active. When, however, the paper holder 42 has been moved into its terminal

position and the control bracket 435 has acted upon the control slide 437, the latch member 421 will be released as shown in Fig. 16. Hence when this particular cycle of operation of the printing machine is completed and the actuating link 205 moves rearwardly from its position shown in Fig. 16 to that shown in Fig. 15, the resulting actuation of the auxiliary control lever 430 permits the spring 439 to actuate the release lever 415, and hence the retaining mechanism 360 is released at the end of the machine cycle and the paper holder 42 is rapidly returned to its loading position.

It has been pointed out hereinbefore that when the last printing impression is made on a sheet or form F the operation of the printing machine must be stopped in the event that it has been operating continuously under control of the auto-stop mechanism, and in accordance with the present invention this end is attained through utilization of the control slide 437. To this end the control slide 437 has a laterally projecting arm 455 thereon as shown in Fig. 6, and at its end the arm 455 has a forwardly extending finger 456 which extends through an opening 457 in the mounting bracket 441. The finger 456 is arranged to engage an insulating block 458 on one arm 459 of a normally closed spring contact switch 460 which is mounted on the forward face of the mounting bracket 441. The switch 460 has wires 461 and 462 connected to its two terminals, and these wires extend in the form of a covered connecting cord 462' to a connector plug 463. The connector plug 463 is adapted to be inserted in a connector outlet 464 located in the end of the machine frame 423 of the printing machine 40, as shown in Fig. 1 of the drawings. The connector outlet 464 has its terminals connected by wires 466 and 467 to the wires 186 and 188, respectively, and hence the control switch 460 is connected in parallel across the control switch 187. Thus the switch 460 constitutes a detecting switch which in the present instance detects movement of the paper holder 42 into its terminal position. When the paper holder 42 is moved out of its terminal position, the spring 439 acts on the control slide 437 to open the switch 460, as shown in Fig. 5 of the drawings. It will be evident, however, that when the control bracket 435 acts on the control slide 437 to shift the control slide rearwardly, the switch 460 will be allowed to close, thereby to energize the auto-stop solenoid 181 so as to cause the printing machine to stop at the end of the cycle of operation. Thus the control slide 437 not only causes automatic return of the paper holder 42 but also causes operation of the printing machine to be stopped at the time when such automatic return of the paper holder takes place.

In certain instances the operator may desire to initiate return movement of the paper holder 42 before the last impression is made on the form F, and in accordance with the present invention this end may be attained through rearward actuation of both of the levers 430 and 421'. The present invention, however, makes provision whereby the operator may conveniently impart such rearward movement to the levers 421' and 430 while remaining seated in front of the printing machine. For this purpose an actuating lever 470 is pivoted at 471 on an upstanding arm 472 carried on the link 205 near the forward end thereof. The lever 470 has one arm 470' which extends forwardly and carries an actuating handle 473 on its forward end. The other arm 470''

extends downwardly along the rear edge of the upstanding arm 472 so that its lower end extends through a slot 474 formed in the upper wall of the link 205. In this connection it will be observed that the link 205 is of an inverted U shaped or channel-like form, and a slide rod 475 is supported within the inverted channel by cross pins 476. The slide rod 475 is urged in a forward direction by a spring 477 acting between an anchor pin 478 on the slide rod 475 and a cross pin 479 secured in the link 205. The action is such that the forward end of the rod 475 engages the lower end of the arm 470" to maintain the same against the stationary mounting arm 472. When the operator wishes to initiate return movement of the paper holder, the handle 473 is depressed, and the rod 475 is thereby urged rearwardly. At its rear end the rod 475 is turned downwardly as at 480 and has a bracket 481 mounted thereon. The bracket 481 has a laterally projecting arm 482 thereon which extends beneath the arm 451 of the bracket 450. Thus, when the mechanism has come to rest at the end of a machine cycle, the handle 473 may be actuated to urge the rod 475 rearwardly from the position shown in Fig. 5 to actuate the latch 421. It will be observed that the lever 430 will be in its actuated position, and hence the actuation of the latch 421 will immediately cause such movement of the release lever 415 that the retaining mechanism 360 will be released and the paper holder 42 will be returned to its loading position.

When the paper holder 42 has been returned to its loading position, the paper clamps 212 may be released by manual actuation of the release lever 221, or in accordance with the present invention such release of the paper clamps 212 may be effected automatically as an incident to the return of the paper holder to loading position. Thus, as shown in Figs. 2 and 23 to 27, means are provided for automatically rocking the cam shaft 212" as the paper holder 42 moves into its loading position to cause opening of the clamps 212. In accomplishing this result an arm 481 is fixed on the cam shaft 212" in an upwardly projecting relation such that a laterally projecting pin 482 on the arm 481 will strike an abutment structure 483 when the paper holder 42 is moving forwardly into its loading position, and such engagement restrains the upper end of the arm 481 against continued movement with the paper holder so that a clamp-releasing rotative movement is imparted to the cam shaft 212" as the paper holder completes its forward movement to loading position.

In the present instance the arm 481 is mounted on the left hand end of the cam shaft 212", and hence the manual operating means which comprise the arm 221' and the lever 222' have been associated with the cam shaft at the right hand end thereof, as shown in Figs. 2, 23 and 25. Thus when the release arm 221' is actuated downwardly and rearwardly, either by manual engagement of the arm 221' or by the automatic action of the arm 481 and the cooperating abutment structure 483, a pin 485 on the arm 221' engages a face 486 on the rear end of the lever 222', thereby elevating the forward end of the lever 222'. When the paper clamps are to be closed, the forward end of the lever 222' is depressed so as to raise the pin 485 and cause rocking of the cam shaft to its position of Fig. 24.

In some instances the arm 221' and the lever 222' may be replaced by other manual actuating

means arranged for application of the manual operating force in a more convenient location. Thus, as shown in Figs. 2 and 23 an operating rod 487 is extended forwardly from the arm 481 so that a knob 488 on the forward end of the rod 487 may be grasped by the operator to shift the rod longitudinally and thereby impart rocking movement to the cam shaft 212". In the present instance the rod 487 is extended along a forwardly projecting handle 490 carried on the paper holder 42 at the left hand end of the cross member 211, the handle 490 having a laterally projecting arm 491 through which the rod 487 is slidably extended. At its rear end the rod 487 is connected to the arm 481, and where automatic clamp releasing means are employed, this connection is afforded by bending the rod 487 laterally so as to extend through an opening in the arm 481 and afford the pin 482.

Where the arm 481 constitutes an element of an automatic clamp releasing means, a spring 492 is connected between a stationary spring anchor 493 and an anchor 494 on the arm 481, and the arrangement of the spring 492 is such that when the paper clamps 212 are closed the spring 492 is ineffective to apply rotative force to the cam shaft in a clamp releasing direction. When, however, the arm 481 is rocked in a rearward or clamp releasing direction by either the manual or automatic means, the disposition of the spring 492 is so altered that it acts to continue such clamp releasing movement of the cam shaft. Thus the operation of the manual releasing means and of the automatic releasing means are improved by the action of the spring 492.

When the arm 481 and the abutment structure 483 cooperate in producing clamp releasing movement of the cam shaft 212", the relation and arrangement of the engaged parts are such that after the release of the paper clamps has been accomplished, the cooperating parts move out of engagement so as to be in condition for closure of the paper clamps when a new sheet or form has been put in place. Furthermore, the cooperating parts of the automatic clamp releasing means are arranged for active cooperation only during the return stroke of the paper holder and this end has been accomplished through making one of the cooperating elements yieldable and hence inactive when these elements engage during the other or advancing movement of the paper holder.

The yieldable element of the automatic clamp releasing means is, in the present instance, incorporated in the abutment structure 483, which as shown in Figs. 23, 26 and 27 comprises a mounting bracket 495, secured by screws 496 to the table top T, and having an abutment arm 497 pivoted thereon by a pivot pin 498. The abutment arm 497 is pivoted intermediate its ends, and near its lower end the arm 497 has a laterally projecting ear 499 adapted to engage the forward edge of the bracket 495 to limit clockwise movement, Fig. 26, of the abutment arm 497. A spring 500 acting between the ear 499 and a spring anchor 501 normally maintains the abutment arm 597 in the upright active position shown in Fig. 26.

In this position a laterally extending abutment ear 502 on the arm 497 is disposed in the path of the pin 482, Figs. 23 and 26, so that as the paper holder approaches its loading position the pin 482 will strike the abutment ear 502. As the movement of the paper holder continues

the arm 481 is rocked from the position shown in Fig. 26 toward the position shown in Fig. 27, and as the spring 492 becomes effective, this movement of the arm 481 is continued until the pin 482 is disposed below the level of the lower edge of the abutment ear 502. Hence the pin 482 may pass beneath the abutment ear 502, and the arrangement is such that when the movement of the paper holder is terminated, the pin 482 is located forwardly of the ear 502. Thus when a new sheet has been located in position in the clamps 212, the cam shaft 212" may be rocked in a clamp-applying direction, and in such movement the pin 482 on arm 481 will clear the abutment ear 502 and will move to the dotted line position shown in Fig. 27.

When the pin 482 is thus positioned it is located so that it will strike the abutment ear 502 as the paper holder is advanced, but when such engagement takes place the abutment arm 497 is merely rocked in a counter-clockwise direction, Figs. 26 and 27, against the biasing action of its spring 500. After the pin 482 has passed the ear 502, the arm 497 is returned by its spring 500 to its active position of Fig. 26. The actuation of the cam shaft 212" to close the clamps 212 may, of course, be accomplished by the control rod 487, or if desired, the control lever 222' may be employed, and in such an instance the control rod 487 may be eliminated as indicated in Figs. 26 and 27 wherein the control rod is illustrated in dot-dash outline.

Operation

When an operator wishes to use the lister 41 with a printing machine 40, the lister housing 200 is mounted on the upper rear corner of the printing machine frame 43, resting the mounting feet 246 and 249 on the mounting rail 250 while the headed stud 251 engaged with the keyhole slot 253 formed in the rear wall 201 of the printing machine frame. The head 252 of the stud 251 is projected through the large end of the keyhole slot 253, and the entire housing 200 is then shifted to the right so as to engage the head 252 with the narrow portion of the slot. The fastening screws 258 are then screwed into the threaded bores 259 in the mounting bar 250, thereby to secure the lister housing 200 in position. The guide member 202 is then fitted into the groove between the two ribs 263 and is shifted rearwardly until the rear end of the guide member 202 moves past the forwardly projecting and unflanged ends 276' of the guide plates 276 and the rear end of the guide member 202 moves into contact with shoulders 276" formed on the guide plates 276 at the forward extremities of the flanges 277, as shown in Figs. 14, 15, and 16. The fastening screws 265 are then tightened so as to hold the guide member 202 in a fixed position.

A flexible rack 203 is then selected which has a line spacing dimension 291 corresponding to the desired line spacing of the form F upon which the listing operations are to be performed, and the selected flexible rack 203 must also have the control bracket 435 thereon in such a position that it will initiate automatic return movement of the paper holder 42 after the desired number of printing impressions have been made upon the form F which is to be employed. The rear end of the flexible rack 203 is inserted into the forward end of the guide member 202 so that the marginal edge portions of the rack are disposed within the grooves 218 of the guide

member. After the flexible rack has been moved a substantial distance into the guide member 202, the paper holder 42 is placed in its operative relationship to the flexible rack by insertion 5 of the stud 220 of the rack 203 into the complementary opening in the mounting bar 210. The rearward movement of the flexible rack is then continued, and the guide means such as rollers on the mounting bar 210 are guided into the 10 grooves 218 of the guide member 202. When a mounting operation is taking place in the manner just described the stop member 376 will be in the position shown in Fig. 11, and when the locating surface 273' of the flexible rack encounters 15 the first or upper one of the teeth 272, the sprocket 270 will be actuated in a counter-clockwise direction as viewed in Fig. 8. This actuation may be attained solely through rearward actuation of the flexible rack 203, or the 20 user may grasp the outer disk 249 of the spring return mechanism 340 to impart the requisite counterclockwise movement to the sprocket 270. As this is done the next one of the teeth 272 of the sprocket will engage the rear one of the 25 openings 273 of the flexible rack, and the successive ones of the openings 273 will be engaged by the successive teeth 272 as the rearward movement of the flexible rack 203 progresses. As the sprocket 270 is thus rotated in a counter-clockwise direction, the stop segment 370 will be correspondingly moved at a somewhat slower rate in a clockwise direction from the position 30 shown in Fig. 11, and when this movement has progressed somewhat beyond the position shown 35 in Fig. 8, the stop member 376 will be actuated by its spring 281 to its normal position shown in Fig. 8.

The actuating lever 206 is then operated manually through a complete stroke in a counter-clockwise direction as viewed in Fig. 14, and this 40 locates the flexible rack 203 and the paper holder 42 in one of the relationships which they will occupy during the performance of a printing operation. The shield carrier 330 is then operated or adjusted by means of the knurled nut 336 so that the edge of the shield 333 is located 45 just above one of the openings 290 in the flexible rack. In such adjusting movement the shoulder 338 on the shield carrier 330 engages the 50 downwardly projecting ear 337 on the pawl carrier 300 and hence the pawl carrier 300 is moved with the shield carrier 330 in the relationship shown in Fig. 8.

The actuating link 205 is then connected to 55 the arm 135 of the platen actuating mechanism by inserting the screw stud 207 through the longitudinal slot 208 of the actuating link. The actuating link 205 is then drawn to its most rearward position and the stud 320 is adjusted along the slot 321 of the actuating lever 206 until the stud 320 is in a position to be engaged with the downwardly facing notch 322 formed in the link 205. The connector plug 463 is then inserted into the connector socket 464 to thereby connect 60 the control switch 460 with the auto-stop mechanism of the printing machine.

The paper guide 223 and the paper clamps 212 are then adjusted in accordance with the width of the form F and the desired location of the 65 printing impressions on such form. In the event that the automatic release mechanism is to be employed for operating the paper clamps 212, the abutment structure 483 is secured in place on the table top T so as to be effective to unclamp the paper clamps 212 when the paper

holder 42 is returned to its loading position. If the form F is to constitute a sheet of checks the requisite printing means for the production of the check number, the date, and the signature may be placed into position and rendered operative by withdrawal of the control slide 12. The machine is then in condition for operation, and the paper holder 42 is brought to its loading or forward position so that a form F may be mounted therein. Such return movement of the paper holder may be readily attained by downward actuation of the control handle 473. The magazine M must, of course, be loaded with the printing devices D and after this is done the machine is operated through the requisite number of idle machine cycles through depression of the skip pedal 140. When the first one of the printing device is in such position that an impression may be made therefrom in the next cycle of operation of the machine, the skip pedal 140 is released and the operation of the machine is terminated.

The auto-stop control plunger 180 is then withdrawn, and this acts to initiate continuous operation of the printing machine so long as the control plunger 180 remains in its withdrawn position. In the first machine cycle following the withdrawal of the auto-stop plunger 180, the forward rocking movement of the arm 135 of the platen actuating mechanism will actuate the lever 206 through a full stroke in a forward direction. In this stroke of the lever 206, the pawl mechanism 300 will be operative only during the last portion of its movement when it engages the most rearward one of the openings 290 of the flexible rack. This occurs because when the paper holder 42 is in its loading position, the second one of the openings 290 is disposed beneath the shield 333 and cannot be engaged by the pawls 305. The forward rocking movement of the arm 135 completes the actuation of the paper holder to its first printing location in the first half of the cycle of operation of the printing machine, and hence when the rocking movement of the arm 135 is reversed, the paper holder 42 will remain stationary while the platen roller moves rearwardly across the form F to produce the desired printing impression thereon. This stationary relationship of the paper holder 42 is attained by reason of the action of the retaining mechanism 360 which operates to hold the pinion 361 and the connected gear 362 and the sprocket 270 against movement by the spring return mechanism 340 in a return direction. It will be observed that while the printing impression is being formed the latch 421 is effective upon a release lever 415 to restrain the lever 415 against releasing movement. When the printing operation in the first printing location on the form F has been completed, the bracket 450 on the actuating link 205 will engage the supplemental control lever 430 to rock the control lever 430 in a rearward direction, but since the latch 421 at this time remains in its active position of Fig. 14, the retaining mechanism 360 will remain active and the paper holder 42 is retained against forward or return movement.

In successive cycles of operation of the printing machine this sequence of operation is repeated, and it will be noted that as the rear end of the flexible rack 203 moves downwardly from the position shown in Fig. 8, it moves beneath a guide member 485 suspended between the guide plates 276 upon the cross shaft 242. The guide member

485 thereby acts to maintain the flexible rack out of contact with the pinion 361.

When the form F is being moved into its last or terminal position, the control member 435 on the flexible rack 203 moves into contact with the arm 436 of the control slide 431 to shift the same rearwardly and into actuating abutment with the ear 445 on the latch 421. This takes place in the first half of the cycle of operation of the printing machine, and the rearward movement of the slide 431 also withdraws the switch actuating finger 456 from its contact with the control switch 460. The switch 460 is thus allowed to close, and circuit is completed to the auto-stop solenoid 181. Hence the auto-stop control plunger 180 is actuated to its inward position to thereby cause the continuous operation of the printing machine to be terminated at the end of the cycle.

The rearward actuation of the control slide 431 has, through its actuation of the latch 421, released the latch 421 so that the parts occupy the positions shown in Fig. 16 of the drawings. The spring 431' is, however, operable upon the auxiliary control lever 430 to hold the ear 431 against the arm 415' of the lever 415, and to thereby maintain the release lever 415 in its active position. Hence the spring return mechanism 340 is maintained inactive and the paper holder 42 is held in its terminal position for the performance of the desired printing impression upon the last line or section of the form F. As the printing operation progresses in the last half of this cycle of operation of the printing machine, the surface 452' of the arm 452 which is carried by the actuating link 405 moves into contact with the auxiliary control lever 430 and at the very end of the cycle, the lever 430 is moved to the position shown in Fig. 15 so that the spring 417 may rock the release lever 415 to its inactive position. The retaining mechanism 360 is thereby released, and the spring return mechanism 340 is rendered operative through the sprocket 270 and the flexible rack 203 to impart rapid return movement to the paper holder 42. Such rapid return movement is terminated when the abutment edge 375 of the stop segment 370 engages the spring 384 of the stop member 376. When this occurs the paper holder 42 is located in its loading position, and through manipulation of the clamp operating levers 221 and 222, the completed form F may be removed and replaced by a new form. Where the automatic release means of Figs. 2 and 23 to 27 is employed, the arm 481 will be actuated by the abutment structure 483 and the paper clamps 212 will be thereby released as the paper holder moves into loading position, so that it is merely necessary for the operator to remove the completed sheet from the clamps, and after a new sheet has been placed therein, the clamps 212 are closed by actuation of the lever 222 or the control rod 487.

When an operator desires to print a form F without the formation of printing impression in one or more lines or sections 66 thereof, the auto-stop mechanism of the printing machine is not ordinarily employed, and the successive cycles of operation of the printing machine are initiated through momentary depression of the consecutive control pedal 142. When the operator wishes to skip a particular line or section 66 in the form F, the lister mechanism may be manually actuated through a line spacing movement while the printing machine is idle by forward withdrawing movement of the link 205, this being accomplished by grasping the actuating handle 209. The forward actuating movement of the link 205

is continued until the rear end of the slot 208 engages the stud 207 so that an accurate line spacing movement is attained and the mechanism is conditioned for the succeeding line spacing movement which will be automatically performed. The operation of the printing machine may then be resumed under the control of the pedal 142 or through the use of the auto-stop control plunger 180.

When an operator wishes to initiate return movement of the paper holder prior to the completion of all of the printing impressions which are normally made upon the form F, this may be readily accomplished through downward actuation of the control handle 473. The control handle 473 is used only when the printing machine is at rest, and when the printing machine is being operated through the use of an auto-stop control mechanism, the control plunger 180 is actuated manually to its inward position prior to the actuation of the control handle 473. Where the machine is being operated under control of the foot pedals, the control handle 473 may be actuated at the end of any cycle of operation of the machine. The downward actuation of the control handle 473 is operable to cause return movement of the paper holder 42 since it causes the arm 482 to actuate the latch 421 to released position.

Summary

In view of the foregoing description it will be apparent that the present invention enables the paper holder of a lister to be returned to its loading position by power means, and this invention also enables the power actuated return movements of the paper holder to be automatically initiated at the time when the printing operations upon a particular form have been completed. Moreover, it will be observed that this invention enables the paper to be automatically unclamped from the paper holder upon completion of the desired printing operations, thereby simplifying the use of the lister and correspondingly increasing the production rate of the machine as a whole. The lister of the present invention is adapted for convenient and ready association with a printing machine and the arrangement is such that when the lister has been adjusted for the performance of listing operations upon a particular sheet or form, this adjustment is preserved when the lister is removed from the printing machine. Hence the lister may be readily returned to its operative position on the printing machine when further listing operations on the particular form are to be accomplished. The automatic return mechanism of the present lister is such that it may also be rendered operative manually to cause return movement of the paper holder of the lister.

The present lister is so constituted and arranged that it may be used for listing operations upon forms having different line spacing dimensions, and this result may be obtained through the substitution or replacement of but a single element of the lister. This element which is thus replaced is, in the present embodiment, in the form of a flexible member or rack and the present invention enables this flexible member not only to act in tension to impart advancing movement to the paper holder but also to act in compression to impart the desired return movements to the paper holder. The arrangement of the present lister is such that the connection of the replaceable flexible rack with the operat-

ing mechanism of the lister is facilitated, and when the desired association of the flexible member with the operating mechanism has been completed, the operating mechanism is automatically returned to its normal relationship so as to be in condition for operation.

Through the use of the lister of the present invention the paper holder is returned to its loading position after completion of the listing operation on a particular sheet without effort on the part of the operator. Moreover, the present lister accomplishes the desired return movement at a rapid rate, and by reason of such rapid return, coupled with the simplification of removal and replacement of the sheet which results from automatic release of the clamps, it will be evident that the present lister avoids waste of machine time.

Hence, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims:

I claim:

1. In a printing machine having a printing station at which printing devices may be positioned, means for advancing printing devices one by one and in a step by step manner to said printing station, impression means at said printing station operable through a printing cycle in which an impression is made from the printing device located at said printing station, and a listing mechanism comprising a paper holder in which a sheet of paper may be clamped for feeding movement in an advancing direction from an initial position through a succession of intermediate positions and into a thermal position for the formation of printing impressions on said sheet in at least certain of said positions, means operating to actuate said paper holder in an advancing direction in timed relation to the operation of said impression means, power operated means operable to impart return movement to said paper holder, and means arranged to operate in timed relation to the operation of said impression means to initiate operation of said return means after completion of a printing impression in one of said positions.

2. In a printing machine through which a series of printing devices are adapted to be passed one by one to a printing station, means for advancing printing devices one by one and in a step by step manner to said printing station, impression means for producing printed impressions from a printing device at printing station, actuating means for said impression means including a reciprocating element operable through a reciprocating stroke each time said impression means are operated, and a lister mechanism comprising a lister frame mounted on said printing machine and having a guide member extending from said frame toward said printing station, a paper holder mounted and guided on said guide member, means for clamping a sheet on said paper holder for movement by said paper holder across said printing station, a connecting member guided on said guide member and connected to said paper holder to impart movement thereto, means operated by said reciprocable element to impart movement to said connecting member in one direction, spring means operatively associ-

60
65
70
75

ated with said connecting member to be tensioned by said connecting member as said connecting member is moved in said one direction and tending when thus tensioned to impart movement to said connecting member in the other direction, and a releasable one-way retaining mechanism operable to render said spring means ineffective to impart such movement to said connecting member in said other direction.

3. In a printing machine through which a series of printing devices are adapted to be passed one by one to a printing station, means for advancing printing devices one by one and in a step by step manner to said printing station, impression means for producing printed impressions from a printing device at printing station, actuating means for said impression means including a reciprocating element operable through a reciprocating stroke each time said impression means are operated, and a lister mechanism comprising a lister frame mounted on said printing machine and having a guide member extending from said frame toward said printing station, a paper holder mounted and guided on said guide member, means for clamping a sheet on said paper holder for movement by said paper holder across said printing station, a connecting member guided on said guide member and connected to said paper holder to impart movement thereto, means operated by said reciprocable element to impart movement to said connecting member in an advancing direction, spring means for imparting movement to said connecting member in a return direction, and releasable means operable to render said spring means ineffective to impart such movement to said connecting member in said return direction.

4. In a listing mechanism for use with a printing machine, a lister frame adapted to be mounted in a stationary relation on such a printing machine, a guide member on said lister frame adapted to extend therefrom toward the printing station of such a printing machine, a paper holder mounted for movement along said guide member from an initial position in an advancing direction toward said lister frame, and to a plurality of other positions the last of which constitutes a terminal position, an elongated flexible member being extended along and guided and confined by said guide member and being secured at one end to said paper holder, a sprocket wheel mounted on said lister frame and having teeth adapted for entry into certain successive openings of said flexible member, driving pawl means for cooperation with other openings in said flexible member to actuate said flexible member in such a direction as to impart advancing movement to said paper holder, spring means operating upon said sprocket member to impart return movement to said flexible member in the opposite direction, and releasable means operable to prevent such return movement.

5. In a printing machine having a printing station at which printing devices may be positioned, means for advancing printing devices one by one and in a step by step manner to said printing station, impression means at said printing station, driving means operable to drive said printing device advancing means and said impression means continuously through a succession of cycles in which impressions are made from at least certain of the printing devices as they are located at said printing station, control means for terminating such continuous operation of said machine at the end of one of said cycles,

and a listing mechanism comprising a paper holder in which a sheet of paper may be clamped for feeding movement in an advancing direction from an initial position through a succession of intermediate positions and into a terminal position for the formation of printing impressions on said sheet in at least certain of said positions, means operating to actuate said paper holder in an advancing direction in timed relation to the operation of said impression means, means operable to impart return movement to said paper holder, and means arranged to operate after completion of a printing impression in said terminal position on such a sheet to operate said control means to stop operation of the machine and render said return mechanism operable to automatically return said paper holder to said initial position.

6. In a lister for use with a printing machine, a lister frame having an elongated guide member extending therefrom, a paper holder mounted and guided on said guide member for movement therealong, a flexible member connected at one of its ends to said paper holder and extending along said guide member to said frame, a sprocket member mounted on said frame, said flexible member having openings formed therein at spaced intervals for operative engagement with the teeth of said sprocket member, guide means for maintaining said flexible member in such operative engagement with said sprocket member, driving mechanism having driving pawl means, said flexible member having other openings for engagement by said driving pawl means to drive said flexible member in one direction, spring means for imparting movement to said sprocket member to move said flexible rack in the other direction, one-way retaining means operable upon one of said members to prevent such movement in said other direction, and automatic means operable to release said one-way retaining means in timed relation to movements of said driving pawl means and said flexible member.

7. In a lister for use with a printing machine, a lister frame having an elongated guide member extending therefrom, a paper holder mounted and guided on said guide member for movement therealong, a flexible member connected at one of its ends to said paper holder and extending along said guide member to said frame, said guide member being constructed and arranged to maintain said flexible member against flexure where said flexible member is engaged by said guide member, a sprocket member mounted on said frame, said flexible member having openings formed therein at spaced intervals for operative engagement with the teeth of said sprocket member, guide means for maintaining said flexible member in such operative engagement with said sprocket member, a driving pawl means, said flexible member having other openings for engagement by said driving pawl means to drive said flexible member in one direction, spring means for imparting movement to said sprocket member to move said flexible rack in the other direction, one-way retaining means operable upon one of said members to prevent such movement in said other direction, and means for releasing said one-way retaining means.

8. In a lister for use with a printing machine, a lister frame having an elongated guide member extending therefrom, a paper holder mounted and guided on said guide member for movement therealong, a flexible member connected at one

of its ends to said paper holder and extending along said guide member to said frame, a sprocket member mounted on said frame, said flexible member having openings formed therein at spaced intervals for operative engagement with the teeth of said sprocket member, guide means for maintaining said flexible member in such operative engagement with said sprocket member, a driving pawl means, said flexible member having other openings for engagement by said driving pawl means to drive said flexible member in one direction, spring means for imparting movement to said sprocket member to move said flexible rack in the other direction, friction means operable upon one of said members to prevent such movement in said other direction, and means for releasing said friction means.

9. In a printing machine through which a series of printing devices may be passed one by one to a printing station, means for advancing printing devices one by one and in a step by step manner to said printing station, impression means for making printing impressions from printing devices at printing station, a paper holder upon which a sheet may be clamped for movement past printing station, means operable in timed relation to said impression means to move said paper holder in an advancing direction and in a step by step manner from an initial position to a succession of other positions the last of which constitutes a terminal position, and means arranged to operate as an incident to the performance of a printing operation after said paper holder has reached said terminal position to impart rapid return movement to said paper holder to said initial position.

10. In a printing machine through which a series of printing devices may be passed one by one to a printing station, means for advancing printing devices one by one and in a step by step manner to said printing station, impression means for making printing impressions from printing devices at printing station, a paper holder upon which a sheet may be clamped for movement past printing station, means operable in timed relation to said impression means to move said paper holder in an advancing direction and in a step by step manner from an initial position to a succession of other positions the last of which constitutes a terminal position, return means for said paper holder operable to return the same rapidly from any of its said other positions to said initial position, automatic control means arranged to operate to initiate operation of said return means as an incident to the completion of a printed impression after said paper holder has reached said terminal position, and manually actuated means operable to initiate operation of said return means when said paper holder is in any of its said other positions.

11. In a printing machine through which a series of printing devices are adapted to be passed one by one to a printing station, impression means operable through a printing cycle to produce a printing impression from a printing device at printing station, a listing mechanism mounted on said printing machine and including a paper holder on which a sheet may be clamped for feeding movement in an advancing direction from an initial position relative to said printing station through a plurality of other positions including a terminal position, actuating means including an operating member and a connecting element and operated in timed relation to the operation of said impression means to impart step

by step advancing movement to said paper holder, means for imparting automatic rapid return movement to said paper holder, and means for initiating operation of said automatic return means including a conditioning member operated by said connecting element when said paper holder reaches said terminal position to condition said automatic return means for operation and a release means including a control member operated by said operating member after said conditioning member has been operated to initiate operation of said automatic return means.

12. In a printing machine through which a series of printing devices are adapted to be passed one by one to a printing station, impression means operable through a printing cycle to produce a printing impression from a printing device at printing station, a listing mechanism mounted on said printing machine and including a paper holder on which a sheet may be clamped for feeding movement in an advancing direction from an initial position relative to said printing station through a plurality of other positions including a terminal position, actuating means including an operating member and a connecting element and operated by and in timed relation to the operation of said impression means to impart step by step advancing movement to said paper holder, means for imparting automatic rapid return movement to said paper holder, and means for initiating operation of said automatic return means including a conditioning member operated by said connecting element when said paper holder reaches said terminal position to condition said automatic return means for operation, a control member effective when actuated after said conditioning member has been operated to initiate operation of said automatic return means, and means associated with the actuating means and arranged to actuate said control member after completion of each cycle of operation of said impression means.

13. In a lister for use with a printing machine, a lister frame, a guide member extending from said frame, a paper holder movable along said guideway, an elongated connecting element extending along said guideway and connected to said paper holder, said connecting element having a row of uniformly spaced openings therein, a sprocket mounted on said lister frame and having teeth thereon adapted for successive engagement with the successive spaced openings of said connecting element, spring means acting on said sprocket to impart rotation thereto in one direction, stop means adjustable selectively to a first position wherein it limits movement of said sprocket in said one direction to a loading position or to a second position wherein it limits such movement of said sprocket to a normal position, spring means urging said stop means to said second position, said connecting element being adapted to be connected to said sprocket when said sprocket is rotated from said loading position to said normal position, and being adapted to be disconnected from said sprocket as said sprocket is rotated from said normal position to said loading position.

14. In a lister for use with a printing machine, a lister frame, a guide member extending from said frame, a paper holder movable along said guideway, a sprocket mounted on said lister frame in such a position that said guide member is tangentially related to said sprocket, an elongated connecting element extending along said guideway and connected to said paper holder, said

connecting element having a row of uniformly spaced openings therein adapted to become operatively engaged with the teeth of said sprocket as said connecting element is moved along said guide member in an advancing direction toward said sprocket, spring means acting on said sprocket to resist movement imparted to the sprocket by the connecting element as it is thus moved in said advancing direction, stop means adjustable selectively to a first position wherein it limits movement of said sprocket in a return direction by said spring to a loading position or to a second position wherein it limits such movement of said sprocket to a normal position, and spring means urging said stop means to said second position and acting automatically to return said stop to said second position as soon as a flexible element has been connected to said sprocket and has rotated the sprocket from its loading position to its normal position.

15. An actuating member for the paper holder of a listing machine comprising an elongated flexible strip having longitudinally extending row of openings formed therein at uniformly spaced intervals for engagement with the teeth of a control sprocket or the like, said row of openings extending to one end of said member and said member having a locating surface at said end facing away from the adjacent one of said openings and spaced therefrom a distance equal to the spacing of the openings of said row.

16. An actuating member for the paper holder of a listing machine comprising an elongated flexible strip having longitudinally extending row of openings formed therein at uniformly spaced intervals for engagement with the teeth of a control sprocket or the like, said row of openings extending to one end of said member and said member having a locating surface at said end facing away from the adjacent one of said openings and spaced therefrom a distance equal to the spacing of the openings of said row, and said strip having other openings formed at longitudinally spaced intervals therein for use in imparting actuating movement to said member.

17. In a printing machine through which a series of printing devices may be passed one by one to a printing station, means for advancing printing devices one by one and in a step by step manner to said printing station, impression means for producing printed impressions from a printing device at printing station, actuating means for said impression means including a reciprocating element operable through a reciprocating stroke each time said impression means are operated, and a lister mechanism comprising a lister frame mounted on said printing machine and having an elongated guide member, a paper holder mounted and guided on said guide member, means for clamping a sheet on said paper holder for movement by said paper holder across said printing station, a connecting member guided on said guide member and connected to said paper holder to impart movement thereto, drive means mounted on said lister frame and associated with said connecting member to impart movement to said connecting member and through said connecting member to said paper holder, means including a drive link extending from said reciprocating element to said drive means and operating to actuate said drive means and said connecting member to move said paper holder in an advancing direction, spring means associated with said drive means for imparting movement to said drive means and said connecting member in a re-

turn direction, releasable means operable to render said spring means ineffective to impart such movement to said connecting member in said return direction, automatic governing means for said releasable means for releasing the same to thereby render said spring means effective to impart return movement to said connecting member, and manually operable means for similarly releasing said releasable means and including an actuating handle carried by and movable relative to said drive link.

18. In a printing machine through which a series of printing devices are adapted to be passed one by one to a printing station, means for advancing printing devices one by one and in a step by step manner to said printing station, impression means for producing printed impressions from a printing device at printing station, actuating means for said impression means including a reciprocating element operable through a reciprocating stroke each time said impression means are operated, and a lister mechanism comprising a lister frame mounted on said printing machine and having an elongated guide member extending from said frame, a paper holder mounted and guided on said guide member, means for clamping a sheet on said paper holder for movement by said paper holder across said printing station, a connecting member guided on said guide member and connected to said paper holder to impart movement thereto, drive means mounted on said lister frame and associated with said connecting member to impart movement to said connecting member, means including a drive link extending from said reciprocating element to said drive means and operable to actuate said drive means for imparting movement to said drive means and said connecting member to move said paper holder in an advancing direction, power actuated return means associated with said drive means and said connecting member for moving the same in a return direction, releasable detent means normally acting to render said power means ineffective to impart such movement to said connecting member in said return direction, and manually operable governing means for said releasable means including a manually engageable actuating handle carried on said driving link and operable to release said releasable means to thereby render said power means effective to impart return movement to said connecting member.

19. In a printing machine through which a series of printing devices are adapted to be passed one by one to a printing station, impression means for producing printed impressions from a printing device at printing station, actuating means for said impression means including a reciprocating element operable through a reciprocating stroke each time said impression means are operated, and a lister mechanism comprising a lister frame mounted on said printing machine, a paper holder mounted and guided for movement relative to said printing station, means for clamping a sheet on said paper holder for movement by said paper holder across said printing station, drive means mounted on said lister frame and connected to said paper holder to impart movement thereto, means including a drive link extending from said reciprocating element to said drive means and operable to actuate said drive means to move said paper holder in an advancing direction, power actuated return means associated with said drive means for imparting move-

ment to said drive means and said paper holder in a return direction, and means for governing operation of said return means.

20. In a printing machine through which a series of printing devices are adapted to be passed one by one to a printing station, impression means operable through a printing cycle to produce a printing impression from a printing device at printing station, driving means for said printing machine, governing mechanism for causing continuous operation of said printing machine and including a stop element operable when actuated to terminate such continuous operation at the end of the cycle of operation in which such actuation takes place, a listing mechanism mounted on said printing machine and including a paper holder on which a sheet may be clamped for feeding movement in an advancing direction from an initial position relative to said printing station through a plurality of other positions including a terminal position, actuating means for said paper holder arranged to operate in timed relation to the operation of said impression means to impart step by step advancing movement to said paper holder, means for imparting automatic rapid return movement to said paper holder, a control member operatively associated with said stop element to actuate said stop element and thereby terminate said continuous operation of said printing machine, means operating in timed relation to the advancing movements to actuate said control member when said paper holder reaches said terminal position, and governing means including said control element effective to initiate operation of said automatic return means when a printed impression has been completed in said terminal position of said paper holder.

21. In a printing machine through which a series of printing devices are adapted to be passed one by one to a printing station, impression means operable through a printing cycle to produce a printing impression from a printing device at printing station, a listing mechanism mounted on said printing machine and including a paper holder on which a sheet may be clamped for feeding movement in an advancing direction from an initial position relative to said printing station through a plurality of other positions including a terminal position, actuating means operating in timed relation to the operation of said impression means to impart step by step advancing movement to said paper holder, means for imparting automatic rapid return movement to said paper holder, a pair of control elements the concurrent actuation of which is effective upon said return means to initiate rapid return movement of said paper holder, means operating to actuate one of said control elements each time said impression means completes a cycle of operation, and means operating to actuate the other control element when said paper holder reaches said terminal position to thereby place said one control element in control of said automatic return means to cause return movement of said paper holder automatically upon completion of a printing impression in the said terminal position.

22. In a printing machine through which a series of printing devices are adapted to be passed one by one to a printing station, impression means operable through a printing cycle to produce a printing impression from a printing device at printing station, a listing mechanism mounted on said printing machine and including a paper holder on which a sheet may be clamped for

feeding movement in an advancing direction from an initial position relative to said printing station through a plurality of other positions including a terminal position, actuating means operable in timed relation to the operation of said impression means to impart step by step advancing movement to said paper holder, means for imparting automatic rapid return movement to said paper holder, and means for initiating operation of said automatic return means and including a conditioning member operated when said paper holder reaches said terminal position to condition said automatic return means for operation and a supplemental control member operating in timed relation to the operation of said impression means and effective when operated after said conditioning member has been operated to initiate operation of said automatic return means.

23. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to a succession of other positions of which one constitutes a terminal position, clamping means on said paper holder for securing a sheet thereto, means for returning said paper holder to said initial position, a shiftable operating member mounted on said paper holder for movement relative thereto to release said clamping means, a stationarily mounted abutment member adapted in the return movement of said paper holder to be engaged by said operating member to impart clamp-releasing movement to said operating member relative to said paper holder, one of said members being mounted for yielding movement as said members are engaged in the advancing movement of said paper holder, the stationarily mounted abutment member being so positioned that further return movement of said paper holder to said initial position locates the said operating member clear of said stationary abutment member and in a position for clamping movement while said paper holder is in said initial position.

24. In a printing machine through which a series of printing devices may be passed to printing position, means for advancing printing devices to printing position, impression means for making impressions from printing devices at printing position, means including a paper holder for feeding a sheet to printing position and in an advancing direction from an initial position to a succession of other positions, clamping means on said paper holder for securing a sheet thereto, means for returning said paper holder to said initial position, a shiftable operating member mounted on said paper holder for movement relative thereto to release said clamping means, a stationarily mounted abutment member adapted in the return movement of said paper holder to be engaged by said operating member just before it reaches said initial position to initiate clamp-releasing movement of said operating member, and spring means for completing said clamp-releasing movement of said operating member after such movement has been thus initiated, said operating member being free and clear of said abutment member when the paper holder is in said initial position to thereby enable clamping

movement of said operating member while said paper holder remains in said initial position.

25. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to a succession of other positions, clamping means on said paper holder for securing a sheet thereto, means for returning said paper holder to its initial position, operating means for said clamping means including a rockable arm on said paper holder, an abutment structure stationarily mounted and having an abutment arm adapted for operative engagement by said rockable arm in the movements of said paper holder, said abutment arm being yieldingly shiftable by said rockable arm as said paper holder moves in an advancing direction and being effective to impart clamp releasing movement to said rockable arm as the paper holder moves in a return direction, said operating member being free and clear of said abutment member when the paper holder is in said initial position to thereby enable clamping movement of said operating member while said paper holder remains in said initial position.

26. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to a succession of other position, clamping means on said paper holder for securing a sheet thereto, means for returning said paper holder to said initial position, and means operating as an incident to such return to release said clamping means and condition the same for clamping of a new sheet thereby while said paper holder is located in said initial position.

27. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to a succession of other positions, clamping means on said paper holder for securing a sheet thereto, means for manually actuating and returning said paper holder to its initial position including an elongated handle projecting from said paper holder, and operating means for said clamping means including an actuating rod supported in part by said handle and projecting therealong and adapted for movement relative to said handle to apply or release said clamping means.

28. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to

a succession of other positions, clamping means on said paper holder for securing a sheet thereto, and means operating under the joint control of the movements of said paper holder and said impression means to automatically return said paper holder to said initial position and to release said sheet clamping means as an incident to such return.

29. In a printing machine through which a series of printing devices may be passed to printing position, means for advancing printing devices one by one and in a step by step manner to printing position, impression means for making impressions from printing devices at printing position, means including a paper holder for feeding a sheet to printing position and in an advancing direction from an initial position to a succession of other positions, clamping means on said paper holder for securing a sheet thereto, means operating to automatically return said paper holder to said initial position, and means operable as an incident to such return to release said clamping means and condition the same for clamping of a new sheet thereby while said paper holder is located in said initial position.

30. In a lister for use with a printing machine, a lister frame adapted to be mounted on a printing machine and having an elongated guide member, a paper holder mounted on said guide member and guided for movement therewith, means for clamping a sheet on said paper holder for movement by said paper holder across a printing station in such a printing machine, a connecting member guide on said guide member and connected to said paper holder to impart movement thereto, drive means mounted on said lister frame and associated with said connecting member and through said connecting member to said paper holder, means including a drive link extended from said drive means and adapted for connection to a reciprocating element of such a printing machine to actuate said driving means and said connecting member to move said paper holder in an advancing direction, spring means associated with said drive means for imparting movement to said drive means and said connecting member in a return direction, releasable means operable to render said spring means ineffective to impart such movement to said connecting member in said return direction, automatic governing means for said releasable means operating in timed relation to the movements of said paper holder and said drive link to release said releasable means to thereby render said spring means effective to impart return movement to said connecting member, and manually operable means for similarly releasing said releasable means and including an actuating handle carried by and movable relative to said drive link.

31. In a lister for use with a printing machine, a lister frame adapted to be mounted on the frame of such a printing machine and having an elongated guide member extending from said frame, a paper holder mounted on guide on said guide member, means for clamping a sheet on said paper holder for movement by said paper holder across a printing station in such a printing machine, a connecting member guided on said guide member and connected to said paper holder to impart movement thereto, drive means on said lister frame and associated with said connecting member to impart movement to said connecting member, means including a drive link extending from said drive means and

adapted for connection with an element of such a printing machine to actuate said drive means for imparting movement to said drive means and said connecting member to move said paper holder in an advancing direction, power means associated with said drive means for imparting movement to said drive means and said connecting member in a return direction, releasable detent means operable to render said power means ineffective to impart such movement to said connecting member in a return direction, and manually operable governing means for said releasable means including a manually engageable actuating handle carried on said driving link and operable to release said releasable means to thereby render said power means effective to impart return movement to said connecting member.

32. In a lister for use with a printing machine, a lister frame adapted for mounting on such a printing machine, a paper holder mounted and guided for movement on said lister frame relative to a printing station in such a printing machine, means for clamping a sheet on said paper holder for movement across such a printing station, drive means on said lister frame and connected to said paper holder to impart movement thereto, means including a drive link extending from said drive means and adapted to be connected to a reciprocating element of such a printing machine to actuate said drive means to move said paper holder in an advancing direction, power actuated return means associated with said drive means for imparting movement to said drive means and said paper holder in a return direction, and means for governing the operation of said return means.

33. In a lister for use with a printing machine, a lister frame adapted to be mounted on such a printing machine, a paper holder mounted and guided on said lister frame for movement on said lister frame and relative to a printing station in such a machine, means for clamping sheet on said paper holder, said paper holder being movable from an initial position through a plurality of other positions including a terminal position, actuating means on said lister frame

adapted for operative connection with such a printing machine to impart step by step advancing movement to the paper holder means for imparting automatic rapid return movement to said paper holder, a pair of control elements the concurrent actuation of which is effective upon said return means to initiate rapid return movement of said paper holder, one of said control elements being adapted to be operated by such 5 means to initiate rapid return movement of said paper holder, one of said control elements being adapted to be operated by such 10 a printing machine near the end of the printing cycle of such a machine, and means on said lister and operating to actuate the other of said control elements when said paper holder reaches said terminal position to thereby place said one control element in control of said automatic return means to cause return movement of the paper holder automatically upon completion of a printing cycle by such a printing machine.

34. In a lister mechanism adapted for use with a printing machine, a lister frame adapted to be mounted on such a printing machine, means associated with said frame and affording a guideway, a paper holder supported and guided on said guideway and on which a sheet may be clamped for feeding movement from an initial position relative to a printing station in such a machine through a plurality of other positions including a terminal position, actuating means for said paper holder mounted on said lister frame and 25 adapted for operative association with a printing machine to operate in timed relation to the operation of such a printing machine to impart step by step advancing movement to the paper holder, automatic means for imparting rapid 30 return movement to said paper holder, and means for initiating operation of said automatic return means and including a conditioning member operated when said paper holder reaches said terminal position to condition said automatic return means for operation and a supplemental control member arranged for operation by such a printing machine in each cycle thereof and effective when operated after said conditioning member has been operated to initiate operation of said automatic return means.

CARL J. HUEBER.
